UNITED STATES PATENT OFFICE

ESMOND P. G. WRIGHT, OF CROYDON, ENGLAND, ASSIGNOR TO WESTERN ELECTRIC COMPANY, INCORPORATED, OF NEW YORK, N. Y., A CORPORATION OF NEW YORK

TELEPHONE EXCHANGE SYSTEM

Application filed November 12, 1930, Serial No. 495,062, and in Great Britain December 18, 1929.

This invention relates to telephone exchange systems and more particularly to measured service telephone systems in which metering is effected automatically in accordance with the zone within which the called subscriber's station is located with respect to the calling subscriber's station.

The object of this invention is to provide simple and efficient means for determining and registering the charge to be made on calls to different points all of which are reached in part over a single group of trunks.

According to this invention means are provided for controlling the operation of a selector switch so that the brushes are advanced to the same group of trunks in response to pulses corresponding to any one of a plurality of digits. For instance on calls completed in part over a single group of trunks to a tandem point the dialing of any of several different digits is effective to cause selection of this group of trunks.

Another feature of this invention resides in an arrangement whereby a single group of trunks is selected in response to impulses corresponding to any one of a plurality of digits, these impulses being at the same time effective to determine the charge to be made for the establishment of the call, the charge being varied according to the number of impulses received. Thus in extending calls to and through a tandem office the transmission of any one of several different digits causes the selection of the same group of trunks to the tandem office but the charge to be made for each call depends upon its destination beyond the tandem office and this is indicated by the number of impulses received.

The features of this invention will be better understood from the following description of a telephone system in which the invention is applied. This system, which is shown diagrammatically in the drawings, is a controller bye-path system equipped with a register-translator for use on certain classes of calls. It is understood, however, that modifications and other applications of the invention will readily occur to one skilled in the art.

Referring to the drawings:

Fig. 1 shows a subscriber's station A and line circuit LC, a primary finder LF1, a secondary finder LF2, a group and start unit G, and a pre-selector D.

Fig. 2 shows a first selector stage comprising a conversational switch CS1 with which the secondary finder of Fig. 1 is permanently associated, and a bye-path control unit C1 which is common to a group of conversational switches including the one shown. The conversational switch is separated from the control unit by the broken line.

Figs. 3 and 4 show a second selector stage comprising a conversational switch CS2 and a second stage bye-path control unit C2 which is common to a group of switches including the switch CS2. The broken line separates the conversational switch from the common control unit.

Figs. 5 and 6 show a register-translator unit RT which is common to a plurality of second stage control units including the unit C2.

Figs. 7 and 8 show an intermediate selection stage comprising the conversational switch CS3 and a bye-path control unit C3 which is common to a group of switches including the switch CS3. The broken line separates the conversational switch from the control unit.

Fig. 9 shows an outgoing trunk repeater TR for use on calls to tandem offices.

Fig. 10 indicates how Figs. 1 to 9 are to be placed to form the complete system to which this description relates.

Referring to Fig. 1, A represents a subscriber's station which is equipped with a subset of the usual type having a dial for use in automatically establishing telephone connections. The line from this station terminates at the exchange in a line circuit LC, in the banks of primary finders, such as LF1, and also in the banks of connector switches, which are not shown. The line circuit LC includes the usual line and cut-off relays and also includes a message register. The subscribers' lines are divided into groups and there are as many lines in a group as there are sets of terminals in the banks of the primary line finders. The primary finder switches

55

60

65

70

80

85

90

95

100

comprise 100 point single-motion step-by-step switches of the no-normal type having two sets of wipers arranged 180° apart, each wiping over an arc of 50 terminals during one 5 complete revolution of the switch shaft. The finder LF1 includes a stepping magnet 10 and the brushes numbered 11, 12 and 13 together with corresponding banks of terminals.

The lines in each group are multiplied to 10 the banks of as many primary finders as are required to handle the traffic from that group. A group unit G is associated with each group of lines; this unit includes a start relay 6 for starting an idle pre-selected secondary finder 15 in search of a primary finder whenever a call is originated over any of the lines in the group.

The secondary finder switches are similar 20 to the primary finder switches; the finder LF2 includes a stepping magnet 40 and brushes numbered 41 to 46 inclusive together with corresponding banks of terminals. The secondary finders are linked to conversational switches of a first selecting stage and are divided 25 into groups each of sufficient size to handle the traffic which will be directed through them. Each secondary group is arranged to search for a different primary finder in each of the primary groups. Associated 30 with each group of secondary finders is an allotting and controlling switch D which pre-selects an idle secondary finder linked with a first stage selector and having an associated control circuit which is also idle. Preferably, therefore, the number of pre-selecting 35 switches is equal to the number of groups of secondary finders and to the number of primary finders in each group. The pre-selector D which includes the stepping magnet 20 and the brushes numbered 21 to 28 inclusive together with corresponding terminal banks, is also a single-motion step-by-step switch having no normal position.

When a subscriber originates a call, the 40 starting relay in the associated group circuit marks all the primary finders serving the group in which the call originates, and starts a set of secondary finders, which have been pre-selected by the switches D, in search of an 45 idle primary finder. These secondary finders hunt until two of them have reached marked primary finders; and those two primary finders then hunt until one of them finds the calling line.

The conversational switch CS1 of the first 50 selecting stage is a 100 point single-motion step-by-step switch having a stepping magnet 50 and wipers 51 to 54 inclusive, together with corresponding banks of terminals. The control unit C1 comprises a control switch R1, a bye-path switch R2 and an associated group of relays. The control switch R1 is a 55 point step-by-step single-motion switch, the terminals being strapped so that in one 60 complete revolution of the switch there are as

many cycles of operation as the capacity of the switch permits; this switch includes the stepping magnet 60 and wipers numbered 61 to 65 inclusive together with corresponding banks of terminals. The bye-path switch R2 70 is a 100 point single-motion step-by-step switch having a stepping magnet 70 and wipers numbered 71 to 76 inclusive together with corresponding terminal banks. There are two sets each of the wipers designated 71, 72, 73 and 74, both sets being effective to simultaneously wipe over corresponding banks of terminals. Certain groups of positions of the switch R1 are used to effect a marking in the bank of the bye-path switch R2, the terminals in these positions of the bank 65 being connected as required to the terminals in the control bank 75 of switch R2. Other groups of positions of switch R1 are used for operatively connecting the control circuit with a particular conversational switch to which a calling line has been extended and through which the control circuit is receiving impulses created by the operation of the dial at the calling subscriber's station; the terminals in these positions of the marking banks 74 are multiplied to corresponding terminals in the marking bank 51 of all the conversational switches served by the control unit C1. Outgoing talking conductors extend from the banks 51 and 52, to the conversational switches of the succeeding switching stage. Corresponding line and test conductors extend from the banks 71, 72 and 73 of bye-path switch R2 to the switches of the succeeding switching stage. Holding conductors extend from the terminals in the bank 53 of switch CS1 to the conversational switches of the succeeding switching stage.

The control switch R1 is advanced under control of the impulses created by the dialing of the first digit of the called number to a corresponding position; whereupon the bye-path switch R2 is advanced to the group of terminals thus marked in the banks 74. The R2 switch is then advanced automatically to select a set of terminals in the marked group, the test terminal of which is connected through an idle conversational switch of the succeeding selecting stage to an idle control unit. The incoming impulse leads are thus immediately extended through brushes 71 and 72 to the succeeding bye-path control circuit. The R1 switch is then again advanced until it finds the terminals of the conversational switch of the first selecting stage to which the calling line is connected. Whereupon the switch CS1 is advanced until its test brush 54 makes contact with the marked terminal corresponding to the set of terminals selected by the bye-path switch R2. Both the control and conversational connections are thus extended to the succeeding selecting stage.

The conversational switch CS2 of the sec-

ond selecting stage, shown in Fig. 3, is similar to the switch CS1 of the first selecting stage; it includes the stepping magnet 100 and the brushes 101, 102, 103 and 104 together with corresponding banks. The control unit C2, shown in Figs. 3 and 4, includes the control switches RM1 and RM3 and the bye-path switch RM2. The control switch RM1 is similar to the control switch R1 of the first selecting stage; it includes the stepping magnet 110 and the brushes numbered 111 to 119 inclusive, together with corresponding banks of terminals. The bye-path switch RM2 is similar to the bye-path switch R2 of the first selecting stage; it includes the stepping magnet 120 and the brushes numbered 121 to 126 inclusive together with corresponding banks of terminals. The control switch RM3 is similar to the bye-path switch RM2; it includes the stepping magnet 140 and the brushes numbered 141 to 148 inclusive together with corresponding banks of terminals.

The register-translator unit RT, shown in Figs. 5 and 6, includes a finder switch RF by means of which the register-translator may be connected to any one of the group of second stage control units with which it is associated. It also includes a code switch CM, a numerical switch NS, three sets of register relays, and a sender switch SM. The finder switch RF is a single-motion step-by-step switch having no home position; it has a stepping magnet 200 and brushes numbered 201 to 210 inclusive, together with corresponding banks of terminals. The code switch CM is a single-motion step-by-step switch having a normal position; it has a stepping magnet 220 and brushes numbered 221 to 225 inclusive, together with corresponding banks of terminals. The numerical switch NS is a single-motion step-by-step switch having a normal position; it has a stepping magnet 240 and brushes numbered 241 to 247 inclusive, together with corresponding banks of terminals. There are three sets of register relays numbered respectively from 251 to 254 inclusive, from 261 to 264 inclusive and from 271 to 274 inclusive. These sets register respectively the thousands, hundreds, and tens digits of a called number in accordance with corresponding advances of the numerical switch NS. The units digit of a called number is registered by the numerical switch and does not need to be transferred since all of the dial impulses have then been received. The sender switch SM is a single-motion step-by-step switch having a normal position; it has a stepping magnet 280 and brushes numbered 281 to 285 inclusive together with corresponding banks of terminals.

The second stage control unit receives the second and third digits of the office code, and during receipt of the third digit a starting

signal is extended to a number of register-translators causing their various finder switches RF to search for the control unit from which the starting signal was received. The second office code digit is stored by the RM3 switch under control of switch RM1, and the bye-path switch RM2 selects the corresponding outgoing trunk group under control of switch RM3. Switch RM2 then automatically selects an idle set of terminals in this group, the test terminal of which leads to a conversational switch of the succeeding selecting stage. The third office code digit is stored by the RM3 switch.

If the call is a local call the register-translator is released as soon as the connection is extended through the bye-path switch RM2 to a succeeding local selecting stage. If the call is an interoffice call reached over direct trunks and an idle trunk is immediately available, the register-translator is also released as soon as the connection is extended through the bye-path switch RM2; but if an idle trunk is not found before the next digit is dialed, the numerical digits are stored in the register-translator and retransmitted by its sender switch to complete the connection. If the call is one which may be completed over alternative routes,—that is, either over a direct trunk selected by the bye-path switch RM2 or over a trunk selected at the intermediate outgoing selecting stage, the register-translator is released if an idle direct trunk is immediately available. But, if all direct trunks are busy, the office code digits are retransmitted by the control unit C2 to the register-translator at the same time that the numerical impulses are being received; the control unit C2 then operates to advance the bye-path switch RM2 to a group of terminals connected to an intermediate outgoing selecting stage, and the completion of the connection is controlled by the register-translator. If the call is one which is completed only through the intermediate selecting stage, the office code and numerical digits are received by the register-translator and the bye-path switch RM2 advances to the group of terminals leading to the intermediate selecting stage. If the call is one which is completed through a tandem office, the intermediate selecting stage is effective to select the group of trunks which lead to this tandem office although the impulses transmitted by the register-translator to control the selection are varied in accordance with the particular called office to be reached through the tandem point.

The intermediate selecting stage, shown in Figs. 7 and 8, comprises a conversational switch CS3, a bye-path control unit C3, and a metering control switch Z. The control unit C3 comprises a control switch and a bye-path switch IR2. The switches CS3, IR1 and IR2 are similar to the switches CS1, R1 and R2 of the first selecting stage shown in Fig. 2.

The switch CS3 has a stepping magnet 300 and brushes numbered 301, 302, 303 and 304 together with corresponding banks of terminals. The switch IR1 has a stepping magnet 320 and brushes numbered 321 to 327 inclusive, together with corresponding banks of terminals. The IR2 switch has a stepping magnet 350 and brushes numbered 351 to 355 inclusive, together with corresponding banks of terminals. The Z switch is a single-motion step-by-step switch having no normal position; it has a stepping magnet 370 and brushes numbered 371 to 374 inclusive, together with corresponding banks of terminals. The selecting operation of the outgoing stage is completed in response to impulses received from the register-translator of the second switching stage in a similar manner to that in which the selecting operation of the first stage is completed in response to the impulses created by the dialing of the first digit of the office code. The IR1 switch is also effective to operate the charge control relays 307 and 308 of the switch CS3 according to the position to which the IR1 switch is advanced by the impulses from the register-translator. When the supervisory relay 306 of the switch CS3 operates in consequence of the answer of the called subscriber, a starting signal is transmitted to the charging switch Z whereby this switch, which is common to a group of conversational switches such as CS3, hunts for and connects to the particular switch whose supervisory relay has operated. The charge control circuit is then effective, under control of relays 307 and 308 of the conversational switch to operate the calling subscriber's register the required number of times.

The outgoing truck repeater TR shown in Fig. 9 transmits the remaining impulses sent out from the register-translator RT over the outgoing trunk to the distant tandem office T. The tandem office may be equipped with any of the well known types of automatic telephone apparatus which responds to incoming trains of impulses corresponding to the number of a called station.

The selecting stages for completing local calls or for completing calls which do not make use of the intermediate selecting stage are not involved in the description of this invention and therefore they are not illustrated in the drawings. For the same reason reference to the operation of the second selecting stage and register-translator on these types of calls will be omitted, as far as possible.

The operation of the system shown in Figs. 1 to 9 inclusive will now be described, giving detailed attention to a call which is routed through a tandem office.

When the subscriber at station A removes the receiver to originate a call, an obvious circuit is closed over line 1 for operating the line relay 2. Relay 2 connects the windings of the cut-off relay 3 over conductor 5 to mark the sleeve terminal of the line 1 in the banks of the associated group of primary line-finder switches. Relay 2 also closes a circuit for operating the start relay 6 in group circuit G. Relay 6 connects the windings of relay 7 over conductor 9 to the marking terminal in the banks of all secondary finders in the associated secondary group. Start relay 6 also connects ground at its outer front contact, through the outer back contact of relay 7, over conductor 8 to operate the start relays such as relay 31, of all the idle distributor switches. One of these operating circuits is traced from conductor 8 through the normally closed contact of the left-hand continuity springs of relay 34, left-hand back contact of relay 36 to the winding of start relay 31. Relay 31 closes a circuit for operating relay 32, from ground at the right-hand back contact of relay 35, through the right-hand front contact of relay 31, winding of relay 32, brush 27 of the distributor switch, over conductor 48, left-hand back contact of relay 55, over conductor 67 to the common control unit C1, through the outer left-hand back contact of relay 82, conductor 93, back contacts of relays 86 and 87, conductor 92, inner right-hand back contact of relay 85, brush 65, and normal terminal of switch R1, normal terminal and brush 75 of switch R2, right-hand back contact of relay 82, and through resistance 79 to battery. As soon as this circuit is closed the drop in potential across resistance 79 is sufficient to prevent the selection of any conversational switch in the associated group by another preselector, similar to D, which is hunting for an idle secondary finder as hereinafter described. Relay 32 closes a circuit from battery through the winding and interrupter contacts of the stepping magnet 40 of switch LF2, brush 23, right-hand front contact of relay 32, inner right-hand back contact of relay 36, inner left-hand back contact of relay 34, to ground at the back contact of relay 33. Thus relay 32 and the corresponding relay, of each of the distributor switches which is connected to an idle secondary line-finder, the control circuit of which is idle, close the energizing circuit for the stepping magnet of the associated secondary line-finder switches. Relay 32 also connects ground through its outer left-hand front contact, the next-to-the-outer right-hand back contact of relay 36, winding of test relay 33, and through brush 23 of the distributor switch to brush 45 of the secondary line-finder switch with which the preselector D is connected.

The secondary line-finder LF2 is advanced under control of the stepping magnet 40 from one terminal to another until the brush 45 reaches the marking terminal to which conductor 9 is multipled, whereupon test relay 120

33 in the distributor circuit D is operated. Relay 33 opens the circuit through the winding of the stepping magnet 40 of line-finder LF2 and closes a circuit, for operating relay 34, to ground at the back contact of relay 37. Relay 34 locks through its inner right-hand front contact to ground at the left-hand front contact of relay 31 and disconnects group conductor 8 from the winding of relay 31. Relay 31 is held operated to the ground at the left-hand front contact of relay 34. Relay 7 of the group circuit will not operate in series with the single test relay 33, but when a secondary finder controlled by another distributor switch also engages the marked primary finder, there will be two test relays 31 in parallel and relay 7 will operate and disconnect its left-hand winding from conductor 8 so as to prevent the test relays in other preselecters from operating. When relay 7 operates it opens the operating circuit of the start relays of the remaining distributor switches in the group to prevent further hunting on the part of the remainder of the secondary finders. It is apparent, therefore, that the secondary finders continue to hunt until two of them have seized primary finders of the group having access to the calling line.

If the secondary finder stops on the terminals of a primary finder which is already engaged, the relay 37 operates in a circuit which may be traced from battery through its winding, next to the inner right-hand back contact of relay 36, inner left-hand front contact of relay 32, brush 25 of distributor switch D, brush 44 of finder LF1, terminal of the busy primary line-finder, through the multiple wiring to the corresponding terminal in the bank of another secondary line-finder which has already established connection with this primary finder, over a conductor corresponding to conductor 47, to ground at the front contact of the relay corresponding to relay 56 in the conversational circuit associated with this other secondary finder. Relay 37 operates, holds the circuit for relay 34 open, and closes an alternative circuit for the stepping magnet 40 independent of relay 33 so that the secondary finder switch continues to advance. A primary finder will be taken into use, however, if it is idle even if it is standing on a busy line, since in this case the brush 44 will not be connected to ground at a busy conversational switch.

The aforementioned operation of relay 34 also closes a circuit for the stepping magnet 10 of the primary finder LF1. This circuit may be traced from battery through the winding and interrupter contacts of magnet 10, terminal and brush 46 of line-finder LF2, terminal and brush of bank 21 of the distributor switch D, and through the outer right-hand front contact of relay 34, to ground at the left-hand back contact of relay 35. When one of the two hunting primary finders engages the terminals of the calling lines, a circuit is closed from battery through the windings of cut-off relay 3, in parallel with the winding of the message register 4, over conductor 5, through the terminal and brush 13 of line-finder LF1, terminal and brush 43 of line-finder LF2, terminal and brush 22 of distributor switch D, and through the left-hand winding of relay 35 to ground at the next-to-the-inner right-hand front contact of relay 34. Relays 3 and 35 are operated by the current in this circuit but the message register 4 is marginal and does not operate at this time. Cut-off relay 3 releases line relay 2 by disconnecting its winding from the line. Relay 2 in turn causes the release of relay 6 unless this relay is held operated due to the origination of a call over one or more of the other lines in the group. Relay 35 locks in a circuit from battery through its right-hand winding, and through the next-to-the-outer right-hand front contact of relay 34, to ground at the left-hand front contact of relay 35. Relay 35 opens the circuit for operating the stepping magnet of the primary finder LF1, opens the circuit through the winding of relay 32, and closes a circuit from battery through the winding of relay 36, through the middle right-hand front contact of relay 34 to ground at the left-hand front contact of relay 35. The primary finder LF1 is thus stopped on the terminals of the calling line, relay 32 releases, and relay 36 operates. Relay 36 opens the circuits through the windings of relays 31 and 33 to cause their release; and relay 31 cannot thereafter re-operate if the origination of another call in the same group should cause ground to be reconnected to conductor 8. Relay 31 opens the circuit through the winding of relay 34; and with relays 32 and 34 released, relay 36 is held operated through the normally closed contacts of the right-hand continuity springs of relay 34, inner right-hand front contact of relay 36, over conductor 29 to ground at the back contact of relay 32. The release of relay 34 causes the release of relay 35. Relay 36 closes a circuit for operating relay 56 of the conversational switch CS1 associated with the secondary line-finder used in extending this connection; this circuit may be traced from battery through the winding of relay 56, over conductor 49, through the terminal and brush of bank 28 of distributor switch D, and through the middle left-hand front contact of relay 36 to ground at the right-hand front contact of relay 35.

The aforementioned release of relay 32 closes a circuit from battery through the winding and interrupter contacts of stepping magnet 20 of distributor switch D, through the inner left-hand front contact of relay 36, next-to-the-inner left-hand back contact of relay 34, over conductor 29 to ground at the

- left-hand back contact of relay 32. The distributor switch D is thereby advanced to pre-select an idle secondary finder whose control circuit is also idle in readiness for the next 5 call. When the terminals of such a secondary finder are reached, relay 32 operates in a circuit from ground at the right-hand back contact of relay 35, outer left-hand front contact of relay 36, winding of relay 32, brush 10 27 and terminal of switch D, over conductor 48, through the back contact of relay 55 of the associated conversational circuit, over conductor 67 to the associated control circuit, and thence to idle battery in a similar manner to 15 that hereinbefore described for the operation of relay 32 upon the origination of a call over line 1. Relay 32 opens the circuit for stepping magnet 20 and opens the locking circuit for relay 36. The release of relay 36 in turn 20 causes the release of relay 32. Should the distributor switch D engage a secondary finder which, although idle, has been pre-selected by another distributor switch, relay 37 is operated, before relay 36 releases, in a 25 circuit from battery through the winding of relay 37, next-to-the-inner right-hand front contact of relay 36, brush and selected terminal of bank 24, through the brush 24 of the preselector which has already selected this 30 secondary finder, to ground at the outer right-hand front contact of the relay which corresponds to relay 36. Relay 37 connects ground from the outer right-hand front contact of relay 36 through the right-hand front 35 contact of relay 37 to conductor 29 to hold relay 36 operated and thus continue stepping the preselector brushes past this terminal. Relays 32 and 37 release when the brushes are advanced so that the preselector continues 40 to hunt until another idle secondary finder is reached.
- The aforementioned operation of relay 56 extends the connection from the calling line 1, through brushes 11 and 12 of primary finder LF1 and brushes 41 and 42 of secondary finder LF2, right-hand front contacts of relay 56, conductors 68 and 69, outer left-hand back contacts of relay 88, to the windings of impulse relay 81 of the control unit C1. 45 Relay 81 operates thereby closing an obvious circuit for operating relay 82. Relay 56 also connects ground through its left-hand front contacts, through brush 43 of line-finder LF2 and brush 13 of line-finder LF1 to hold the 50 cut-off relay 3 of the calling subscriber's line operated, and thus prevent release of the connection. Relay 82 connects ground at its outer left-hand front contact to conductor 93, thereby locking relay 56 through its winding 55 and right inner front contact. Relay 82 also opens the test circuit over conductor 67 and through resistance 79, so as to prevent the seizure of any other conversational switch associated with the control unit C1. Relay 60 60 now operates in a circuit which may be

traced from battery through its winding, right outer back contact of relay 88, next-to-the-inner right front contact of relay 82, brush and normal terminal of bank 75 of switch R2, normal terminal and brush 65 of switch R1, inner right back contact of relay 85, over conductor 92, through the back contact of relays 87 and 86, over conductor 93 to ground at the left outer front contact of relay 82. The secondary winding of transformer 70 75 80 85 90 95 100 105 110 115 120 125 130 135 140 145 150 155 160 165 170 175 180 185 190 195 200 205 210 215 220 225 230 235 240 245 250 255 260 265 270 275 to the terminals in bank 75 of switch R2 in such a manner that the circuit for reoperating relay 84 is completed whenever the R2 switch reaches the beginning of the group which corresponds to that on which the R1 switch is standing after all of the impulses created by the dialing of the first digit have been received. The circuit for reoperating relay 84 may be traced from battery through its winding, right outer back contact of relay 88, right outer front contact of relay 82, brush 75 and terminal of switch R2, the corresponding terminal and brush of bank 65 of switch R1, inner right back contact of relay 85, over conductor 92, and through the back contacts of relays 87 and 86 to ground on conductor 93. When relay 84 reoperates in this circuit, it opens the circuit for operating magnet 70 to stop the brushes of switch R2 on the first set of terminals in a group which corresponds to the first digit dialed by the calling subscriber.

The reoperation of relay 84 closes a circuit for operating relay 85; this circuit may be traced from battery through the left-hand winding of relay 85, left outer back contact of relay 91, left-hand back contact of relay 83, right-hand front contact of relay 84, brush and terminal of bank 76 to ground at the right outer back contact of relay 85. Relay 85 closes a locking circuit through its right-hand winding and inner right-hand front contact to ground over conductor 93 before the circuit through its left-hand winding is opened at its outer right-hand back contact. The operation of relay 85 causes the release of relay 84 and connects the windings of test relays 86 and 87 to test brushes 73. If the first set of terminals of the selected group are idle, one or both of test relays 86 and 87 operate, depending upon which of the brushes 73 is in contact with an idle set of terminals. The circuit for operating relay 86 may be traced from ground on conductor 93, through the right outer back contact of relay 91, winding of relay 86, left inner back contact of relay 88, next-to-the-outer right-hand front contact of relay 85, lower brush 73 and first terminal in the selected group, over conductor 98, left outer back contact of relay 105 of the selected conversational switch CS2 in the next switching stage, over conductor 106 to the associated control unit C2, through the left-hand back contact of relay 139, normal terminal and brush 111 of switch RM1, right outer back contact of relay 130, upper brush 124 and the normal terminal of the corresponding bank of switch RM2, and through resistance 127 to battery. The circuit for operating relay 87 may be traced from ground on conductor 93 through the winding of relay 87, middle right-hand back contact of relay 91, next-to-the-inner left-hand back contact of relay 88, middle right-hand front contact of relay 85, through the upper one of test brushes 73 and the first terminal of the selected group, thence over a conductor similar to conductor 98, to battery in a control unit in the same manner as already traced for the operation of test relay 86. The operation of either or both of relays 86 and 87 prevents the further advance of the brushes of switch R2 since the circuit for operating magnet 70 passes through the back contacts of both of these relays. If the first sets of terminals in the selected group are busy, stepping-magnet 70 is reoperated in a circuit which may be traced from battery through its winding, middle right-hand back contact of relay 88, interrupter contacts of magnet 70, right-hand back contact of relay 83, brush 76 and terminal with which it is in contact, right outer front contact of relay 85, conductor 92, and through the back contacts of relays 87 and 86 to ground on conductor 93. The brushes of switch R2 are thus advanced until an idle set of terminals is reached and either or both of relays 86 and 87 operate or until the brushes reach the last of terminals in the selected group. If relay 86 operates it closes an obvious circuit for operating relay 88; and relay 88 locks through its inner right-hand front contact to ground on conductor 93. If relay 87 operates, and relay 86 is not operated, it closes an obvious circuit for operating relay 89; and relay 89 closes an obvious circuit for operating relay 88. Relay 88 locks to ground on conductor 93; and relay 89 is locked through its inner left-hand front contact and the inner right-hand front contact of relay 88 to the same ground. Relay 89 controls the connections to brushes 71, 72 and 74 to render either the upper or lower of these brushes effective, to the exclusion of the others, depending upon whether the selected set of terminals is located in the upper or the lower of the corresponding banks. In the following description we will assume that the selected terminals are located in the lower one of banks 71, 72 and 73 so that relay 89 is not operated. Test relays 86 and 87 are released by relay 88 after it has locked operated.

If all of the terminals of the selected group are busy, a circuit is closed from battery through the winding of relay 84, right outer back contact of relay 88, outer right-hand front contact of relay 82, brush and last terminal in the selected group of bank 75, next-to-the inner right-hand front contact of relay 85, conductor 92, back contacts of relays 87 and 86, to ground on conductor 93. Relay 84 operates in this circuit, to prevent the further operation of stepping magnet 70. Relay 84 closes a circuit from battery through the winding of relay 91, left inner front contact of relay 85, right-hand front contact of relay 84, brush and off-normal terminals of bank 76, through the outer right-hand front con-

tact of relay 85, over conductor 92, and thence to ground as hereinbefore traced. Relay 91 is a slow-to-operate relay so that it will not operate in this circuit during the intervals that both relays 84 and 85 were operated at the time of the initial operation of relay 85; but on the last set of terminals in a group the circuit for relay 91 is maintained so that relay 91 eventually operates and connects busy tone through the secondary winding of transformer 90, right inner front contact of relay 91, middle left-hand front contact of relay 85 in parallel with the left-hand winding of relay 81, so that the all-trunks-busy signal is transmitted to the calling subscriber.

The aforementioned operation of relay 85, at the time of the completion of group selection by switch R2, was also effective to close a circuit for operating stepping magnet 60 of switch R1 so as to advance the brushes of switch R1 into engagement with the set of terminals through which it is connected to the conversational switch CS1. The circuit for operating magnet 60 may be traced from battery through its winding, through the outer left-hand front contact of relay 85, interrupter contacts of magnet 60 to ground at the back contact of relay 66. The stepping magnet 60 is therefore alternately operated and released and the brushes of switch R1 are advanced one step by each release of the magnet 60. When brush 61 makes contact with the terminal associated with switch CS1, relay 66 operates in a circuit which is traced from battery through its winding, brush and terminal of bank 61, right inner front contact of relay 56, over conductor 93 to ground at the left outer front contact of relay 82.

With relays 66 and 88 both operated (due to the fact that the R2 switch has found an idle set of terminals in the required group, and that the control unit C1 is connected through the brushes of switch R1 to the conversational switch CS1), a circuit is completed for operating the stepping magnet 50 of the conversational switch CS1; this circuit is traced from battery through the winding and interrupter contacts of magnet 50, terminal and brush of bank 64 of switch R1, left-hand back contact of relay 84, and through the outer right-hand front contact of relay 88 to ground at the left-hand front contact of relay 66. Relay 66 also connects the ground on conductor 93 through the back contacts of relays 86 and 87, conductor 92, right-hand front contact of relay 66, and through the brush and terminal of bank 65 to the test brush 54 of switch CS1. Magnet 50 advances the brushes of switch CS1 until the test brush 54 comes into contact with the terminal in its bank which is connected to the terminal of the selected set in the bank 74 of switch R2, thereby extending the ground

on test brush 54 through brush 74, the middle right-hand back contact of relay 89, and through the next-to-the-outer right-hand front contact of relay 88, to the winding of relay 84. Relay 84 operates, thereby opening the circuit for operating the stepping magnet 50 so as to stop the brushes of switch CS1 on the terminals of the outgoing conversational switch which was previously selected by the bye-path switch R2. Relay 84 closes a circuit for operating relay 91; this circuit is traced from battery through the winding of relay 91, left inner front contact of relay 85, right-hand front contact of relay 84, brush and terminal of bank 76 of switch R2, right outer front contact of relay 85, conductor 92, back contacts of relays 87 and 86, to the ground on conductor 93. Relay 91 closes a circuit from battery through the winding of relay 55 of conversational circuit CS1, terminal and brush of bank 63 of switch R1, left outer front contact of relay 91, left-hand front contact of relay 84, right outer front contact of relay 88, to ground at the left-hand front contact of relay 66. Relay 55 locks through its right outer and left inner front contacts and through the outer left-hand front contact of relay 56 to ground at the inner left-hand front contact of relay 56. Relay 55 extends the talking connection, from brushes 41 and 42 of line-finder LF2, through its inner right-hand front contacts, through brushes 51 and 52 of switch CS1, over trunk 99 to the conversational switch CS2. It also extends the ground at the inner left-hand front contact of relay 56, through the left outer front contact of relay 56 and the left inner front contact of relay 55, through brush 53 of switch CS1 over the sleeve conductor of trunk 99 to mark the associated conversational switch CS2 in the bank 118 of switch RM1 in the control unit C2.

The aforementioned operation of relay 88, after switch R2 finds an idle set of terminals in the selected group, is effective to disconnect the windings of line relay 81 from the calling line and to extend the connections from the calling line through its outer left-hand front contacts, the inner and outer right-hand back contacts of relay 89, through the lower brushes and selected terminals in banks 71 and 72, over conductors 96 and 97, to the control unit C2 of the succeeding selecting stage. Relay 88 also extends conductor 93 through the left-hand back contact of relay 89, the inner left-hand front contact of relay 88, the next-to-the-outer right-hand front contact of relay 85, through the lower brush and terminal of bank 73, over conductor 98 to the control unit C2. Relays 81 and 82 release in consequence of the operation of relay 88, but relays 56, 85 and 88 (also 89, if operated) are held operated by ground connected to conductor 98 as is hereinafter explained.

Impulses created by the dialing of succeeding digits of the called number are, therefore, transmitted through control unit C1 to control unit C2, until the control unit C2 disconnects this ground from conductor 98, at which time relays 56, 85 and 88 are released. Relay 55 is held operated through its right outer front contact and brush 53 of switch CS1, over the sleeve conductor of trunk 99 to ground in control unit C2 as is hereinafter described. The release of relay 56 causes the successive release of relays 63 and 84 and the release of relay 66 closes a circuit for advancing the R1 switch to normal. The circuit for operating stepping magnet 60 is traced from battery through its winding, left outer back contact of relay 85, left inner back contact of relay 82, right inner back contact of relay 88, off-normal terminals and brush 62 of switch R1, interrupter contacts of magnet 60, to ground at the back contact of relay 66. The release of relay 84 closes a circuit for advancing the R2 switch to normal; this circuit is traced from battery through the winding of stepping magnet 70, middle right-hand back contact of relay 88, interrupter contacts of magnet 70, right-hand back contact of relay 84, brush and off-normal terminals of bank 76, to ground at the right outer back contact of relay 85. With both of switches R1 and R2 in their normal positions, the control unit C1 is made available for use with another of the associated conversational switches since the test conductor 67 is now again connected through resistance 79 to battery.

When the connection from the calling line is extended through brushes 71 and 72 of switch R2 of control unit C1, line relay 131 of control unit C2 is operated in a circuit which may be traced from battery through the right-hand winding of this relay, right outer back contact of relay 165, next-to-the-outer right-hand back contact of relay 166, over conductor 96, through the lower bank and brush 71 of switch R2 in control unit C1, outer right-hand back contact of relay 89, outer left-hand front contact of relay 88, conductor 68, outer right-hand front contact of relay 56, brush 41 of line-finder LF2, brush 11 of line-finder LF1, line 1 and the calling subscriber's sub-set, brush 12 of line-finder LF1, brush 42 of line-finder LF2, middle right-hand front contact of relay 56, conductor 69, next-to-the-outer left-hand front contact of relay 88, inner right-hand back contact of relay 89, through the lower brush and terminal of bank 72 of switch R2, conductor 97, next-to-the-inner right-hand back contacts of relays 166 and 165, through the left-hand winding of relay 131 to ground. Relay 131 closes an obvious circuit for operating the slow-to-release relay 132. Relay 132 closes a circuit for operating relay 130, from battery through the winding of relay

130, right outer back contact of relay 166, over conductor 129, to ground at the front contact of relay 132. Relay 130 opens the aforementioned test circuit through the brush and normal terminal of bank 124 and connects ground through its left outer front contact, the left outer back contact of relay 139, conductor 106, the left outer back contact of relay 105, over test conductor 98, terminal and lower brush 73 of switch R2 of control unit C1, next-to-the-outer right-hand front contact of relay 85, left inner front contact of relay 88, left outer back contact of relay 89, to holding conductor 93 of control unit C1; this ground is effective to prevent the release of relays 55, 56, 66, 84, 85 and 88 as hereinbefore mentioned.

When the calling subscriber dials the second digit, this being one of the digits of the office code, line relay 131 of control unit C2 is alternately released and reoperated as many times as its operating circuit is opened by the contacts of the dial. The release of relay 131 closes a circuit for operating the stepping magnet 110 of switch RM1 and relay 133; this circuit is traced from battery through the winding of stepping magnet 110, right inner back contact of relay 136, right inner front contact of relay 130, winding of relay 133, to ground at the back contact of relay 131. When relay 131 reoperates, the stepping magnet 110 releases but relay 133 is a slow-to-release relay and it remains operated until all of the pulses corresponding to the second digit have been received. Since relay 132 is also a slow-to-release relay it remains operated during receipt of this train of impulses. The brushes of switch RM1 are thereby advanced by the alternate operation and release of magnet 110 to a position which corresponds to the second digit dialed by the calling subscriber.

When the switch RM1 reaches position 2, a circuit is closed for operating the stepping magnet 140 of switch RM3; this circuit is traced from battery through the winding and interrupter contacts of magnet 140, brush and normal terminal of bank 145, over conductor 128, through the second terminal and brush of bank 111 of switch RM1, middle right back contact of relay 136, over conductor 129 to ground at the front contact of relay 132. Stepping magnet 120 of switch RM2 is also operated when the brushes of switch RM1 enter position 2, since the winding of magnet 120 is then connected, through its interrupter contacts and through the brush and normal terminal of bank 126, over conductor 128 to the second terminal of bank 111 of switch RM1. The release of magnets 140 and 120 when their circuits are opened by their own interrupter springs causes the advance of switches RM2 and RM3 from their normal position to position 2. The terminals of bank 112 of switch RM1 are connected in pairs to

the terminals of bank 148 of switch RM3; to illustrate, terminals 2 and 3 of bank 112 are connected to terminal 2 of bank 148, and terminals 4 and 5 of bank 112 are connected to terminal 12 of bank 148. When, therefore, 5 the brushes of switch RM3 are advanced into position 2, a circuit is completed from battery through the winding of relay 134, brush and terminal 2 of bank 148, through terminal 2 or 3 and brush of bank 112 of switch RM1, 10 right-hand back contact of relay 139, to ground at the left inner back contact of relay 158. In operating, relay 134 prevents the closing of another operating circuit for the 15 stepping magnet 140 so that switch RM3 remains in position 2 until switch RM1 has advanced beyond position 3. If, and when the brushes of switch RM1 are advanced beyond position 3 in response to impulses received 20 by line relay 131, relay 134 releases; and the circuit for operating magnet 140 to cause the further advance of switch RM3 is traced from battery through the winding and interrupter contacts of magnet 140, brush and off-normal terminals of bank 145, back contact of relay 25 134, to ground at the left-hand back contact of relay 136. When the brushes of switch RM3 reach position 12, the circuit for operating 30 134 is again closed; and the operation of relay 134 prevents the further advance of switch RM3 until the brushes of switch RM1 have been advanced beyond position 5. The 35 stopping positions 2, 12, 22, etc. of switch RM3 represent the first terminals of different routing groups in the banks 141 and 142. The first and succeeding terminals of each group of terminals in banks 141 and 142 are connected to the first terminal of a corresponding group of terminals in bank 125 of 40 switch RM2. The first terminal of each group in bank 125 is thus continuously marked while the brushes 141 and 142 are engaging the corresponding terminals in their respective banks. This arrangement prevents 45 the advance of switch RM2 beyond the first terminal of the group marked by switch RM3. The winding of relay 149 is connected to terminals 3, 5, 7, 9, and 11 of bank 111 of switch RM1 so that this relay is operated, 50 through brush 111 in each of these positions; to the ground on conductor 129, but the operation of relay 149 during the receipt of the impulses created by the dialing of the second digit is without effect since at this time brush 55 142 is continuously connected through the right outer back contact of relay 136 and the left-hand back contact of relay 168, to ground at the right outer back contact of relay 158.

Having advanced from normal to position 60 2 the further advance of switch RM2 is controlled by relay 135, this relay being connected to operate when brush 125 of switch RM2 engages the terminal marked by brushes 141 and 142 of switch RM3. The circuit for 65 operating relay 135 may be traced from bat-

tery through its winding, right outer back contact of relay 162, brush and marked terminal of bank 125 of switch RM2, terminal and brush of bank 141 or 142, through the left inner front contact of relay 149 or the right outer back contact of relay 136, and through the left-hand back contact of relay 168, to ground at the right outer back contact of relay 158. The circuit for operating magnet 120, after the brushes of switch RM2 have 70 been advanced to position 2, may be traced from battery through its winding and interrupter contacts, brush and off-normal terminals of bank 126, left inner back contact of relay 162, back contacts of relay 135, 75 157 and 156, to ground at the middle left-hand back contact of relay 162. If and when the brushes of switch RM3 are advanced beyond the first group, as controlled by the setting of switch RM1, the stepping magnet 80 120 of switch RM2 will be again energized due to the release of relay 135; and the brushes of switch RM2 will be advanced until they engage the next terminal which is marked by brush 141 or 142 of switch RM3, 85 at which time relay 135 reoperates in the circuit hereinbefore traced. With both of relays 134 and 135 operated and with relay 133 released, a circuit is completed for operating relay 136. This circuit may be traced from 90 battery through the left-hand winding of relay 136, front contact of relay 134, right-hand back contact of relay 133, front contact of relay 135, back contacts of relays 157 and 156, to ground at the middle left-hand back contact of relay 162. Relay 136 closes a locking circuit through its right-hand winding and next-to-the-inner right-hand front contact, to ground at the left inner front contact of relay 130. Relay 136 opens the circuit for 95 operating magnet 140 of switch RM3, disconnects the back contact of relay 131 from the magnet 110 of switch RM1 and connects the back contact of relay 131 to magnet 140 of switch RM3 in readiness for storing the next 100 train of dial impulses.

If switch RM1 stopped in one of positions 3, 5, 7, 9 or 11 so that relay 149 is operated and if the circuit for operating relay 135 passes through brush and bank 142 instead 115 of through brush and bank 141, relay 135 releases when relay 136 operates and relay 149 is locked through its right-hand front contact and the right outer front contact of relay 136, to ground on conductor 129. The release of relay 135 again closes the circuit for operating magnet 120 of switch RM2 so as to advance the brushes of this switch until they reach the terminal which is marked by brush 141 instead of brush 142 of switch RM3. Relay 135 then reoperates to stop further advance of switch RM2. Thus relay 149 controls the marking circuit through brushes 141 and 142 depending upon the first digit dialed. In the following description we will assume 120 125 130

relay 149 to be normal so that brushes 142, 144 and 147 are operatively effective to the exclusion of brushes 141, 143 and 146.

To sum up the operation due to the dialing of the second office code digit relay switch RM1 is advanced to a position which corresponds to the number of impulses received. Switch RM3 is thereby advanced to a corresponding routing group in order to mark a group terminal in the bank of switch RM2. Switch RM2 is thereupon advanced under control of switch RM3 to the first terminal of a group which leads toward the exchange or exchanges indicated by the second office code digit. Relay 184 operates when switch RM3 has been advanced to the terminal marked by switch RM1 and relay 135 operates when switch RM2 has been advanced to the terminal marked by switch RM3.

The aforementioned operation of relay 136 also closes a circuit for operating stepping magnet 110 of switch RM1 to advance the brushes of this switch to connect with conversational switch CS2; this circuit may be traced from battery through the winding of magnet 110, right inner front contact of relay 136, back contact of test relay 137, and interrupter contacts of magnet 110 to ground. The brushes of switch RM1 are thereby advanced by the alternate operation and release of magnet 110 until the terminals associated with the conversational switch CS2 are reached, at which time a circuit is completed for operating test relay 137. Relay 134 releases when switch RM1 advances. The circuit for operating test relay 137 may be traced from battery through the winding of relay 137, resistance 138, brush and terminal of bank 118, back contact of the continuity springs of relay 105, over the holding conductor of trunk 99, through the terminal and brush 53 of switch CS1, the left inner front contact of relay 56, and through both left front contacts of relay 55 to ground. Relay 137 opens the operating circuit for magnet 110 thereby preventing the further advance of switch RM1. Relay 137 also closes an obvious circuit for operating relay 139. Relay 139 disconnects the ground at the left outer front contact of relay 130 from test conductor 98 and connects this ground through the left outer front contact of relay 139, through the brush and terminal of bank 118, back contact of the continuity springs of relay 105 over the sleeve conductor of trunk 99, through brush 53 of switch CS1 and the right outer front contact of relay 55 to the winding of relay 55 to hold this relay operated after relay 56 is released. Relays 56, 66, 84, 85 and 88 of the second selecting stage release when the ground over conductor 98 is thus disconnected by the operation of relay 139 from conductor 93 of control unit C1, thereby causing the return of this control unit to normal as hereinbefore described. The impulsing

circuit from line 1 is now traced through the inner right-hand front contacts of relay 55, brushes 51 and 52 of conversational switch CS1, over the talking conductors of trunk 99, through the terminals and brushes of banks 116 and 117 of switch RM1, the left inner front contacts of relay 139, the back contacts of the right-hand inner continuity springs of relay 166, and through the outer right-hand back contacts of relay 165 to the windings of line relay 131.

When the calling subscriber dials the next digit (the third digit of the office code), relay 131 is alternately released and reoperated in response to the impulses thus created. The first release of relay 131 closes a circuit for operating magnet 140 of switch RM3 and slow-to-release relay 133; this circuit may be traced from battery through the winding of magnet 140, middle left back contact of relay 159, outer left back contact of relay 162, next-to-the-inner left-hand back contact of relay 166, inner left front contact of relay 136, right-hand front contact of relay 130, winding of relay 133, to ground at the back contact of relay 131. The operation of relay 133 closes a circuit for operating relay 150; this circuit may be traced from battery through the winding of relay 150, left outer front contact of relay 136, next-to-the-outer left-hand back contact of relay 166, left outer front contact of relay 133 to ground on conductor 129. Relay 150 locks in a circuit from battery through its winding, the left outer front contact of relay 136, right outer front contact of relay 150, left outer back contact of relay 158, and through the normally closed contacts of the left-hand continuity springs of relay 166, to the ground on conductor 129. Relay 150 sends a start-

ing signal to all of the register-translators associated with the control unit C2 by connecting the ground at the outer back contact of relay 170, through the left outer front contact of relay 150, to conductor 180. Relay 150 also connects battery through the windings of relay 170, the middle left front contact of relay 150, left outer back contact of relay 159, to the test terminal associated with control unit C2 in the bank 209 of the register-translator RT and the corresponding terminals in the banks of the other associated register-translators.

The alternate operation and release of magnet 140, in response to the impulses received by relay 131 from the dialing of the third digit, causes the advance of the brushes of switch RM3 to a corresponding terminal in the previously selected routing group. When relay 133 releases after all of the impulses corresponding to the third digit have been received, a circuit is closed for operating relay 151; this circuit is traced from battery through the winding of relay 151, outer left-hand back contact of relay 133, next-to-the-

outer left-hand back contact of relay 166, outer right-hand front contact of relay 150, and the outer left-hand back contacts of relays 158 and 166, to ground on conductor 129. 5 Relay 151 connects ground through its front contact, the left outer back contact of relay 149, brush 147 and terminal corresponding to the third code digit, to a terminal on the distributing frame DF. The terminals in the banks 146 and 147 of switch RM3 are connected at the distributing frame DF to terminal designated DC, S, CI, AT and D, respectively. Terminals in banks 146 and 147 which do not represent any assigned office 10 code are cross-connected at distributing frame DF to terminal DC; terminals which represent offices reached by trunks directly accessible to switch RM2, including local trunks for completing calls to subscribers 15 in the same office as the calling subscriber, are cross-connected at frame DF to terminal S; terminals, which represent offices reached over call indicator trunks to which switch RM2 has direct access, are cross-connected at 20 frame DF to terminal CI; terminals, which represent offices reached over trunks directly accessible to switch RM2 and also reached over trunks leading to a tandem office in case all of the direct trunks are busy, are cross- 25 connected at frame DF to terminal AT; and terminals, which represent offices reached only over trunks to tandem offices, are cross-connected at frame DF to terminal D. The operation of relay 151 is thus effective on 30 calls for unassigned codes to cause the operation of relay 159, on calls completed over direct trunks only to cause the operation of relay 134, on calls completed over call indicator trunks to cause the operation of relay 35 166, on calls completed over direct trunks and also over tandem trunks to cause the operation of relay 167, and on calls completed only over tandem trunks to cause the operation of relay 168. Since we are only concerned with 40 a call completed over a tandem trunk, we will assume that the terminal with which brush 147 is in contact in cross-connected through frame DF to terminal D so that the operation of relay 151 causes the operation 45 of relay 168; and further reference to the operation of this system on other classes of calls will be omitted as far as possible without detracting from the clarity of the description of this invention. 50

With relay 168 operated, the winding of relay 166 is connected through the right inner front contact of relay 168 in parallel with the winding of relay 168, so that relay 166 operates, and the ground connected from 55 right-hand back contact of relay 158 to the left inner armature of relay 168 is disconnected from brush 142 and is connected to the first terminal of a group in the bank 125 of switch RM2, all of the terminals in this group being connected to trunks leading to 60 an intermediate selecting stage. Relay 135 releases when the ground is disconnected from brush 142 thereby closing the circuit (hereinafter traced) for operating stepping magnet 120 of switch RM2. The brushes of switch RM2 are advanced until brush 125 makes contact with the first terminal of the group outgoing to an intermediate selecting stage, at which time relay 135 reoperates to open the circuit for magnet 120. The circuit for operating relay 135 is traced from battery through its winding, right outer back contact of relay 162, brush and terminal of bank 125, left inner front contact of relay 168, to ground at the right outer back contact 65 of relay 158. The aforementioned operation of relay 166, releases relay 151, closes an obvious circuit for reoperating relay 134, and closes circuits for holding relays 130 and 150 operated. The winding of relay 150 is connected through the outer left-hand front contact of relay 136, the next-to-the-inner left-hand front contact of relay 166, and through the left inner back contact of relay 159, to ground on conductor 129; and the winding 70 of relay 130 is connected through the next-to-the-outer right-hand front contact of relay 166 and the inner right-hand front contact of relay 150 to ground on conductor 129. With both of relays 134 and 135 operated a 75 circuit is closed from battery through the winding and continuity contacts of relay 158, left inner front contact of relay 150, front contact of relay 134, right-hand back contact of relay 133, front contact of relay 135, back contacts of relays 157 and 156, to ground at the middle left-hand back contact of relay 162. Relay 158 operates and locks 80 through the front contact of its continuity springs, back contact of the continuity 85 springs of relay 167, inner right-hand back contact of relay 162, right outer front contact of relay 136, to ground on conductor 129. 90

If either or both of the first sets of terminals in the selected group are idle, either or both of test relays 156 and 157 operate to prevent the further advance of switch RM2. The circuit for operating relay 156 is traced 95 from ground on conductor 129, through the winding of relay 156, right inner back contact of relay 159, next-to-the-outer right-hand front contact of relay 158, lower brush and terminal of bank 123, over a test conductor 100 such as 198, to the selected switch CS3 of the succeeding intermediate selecting stage, through the left-hand back contact of a relay such as 305, over a test conductor such as 313 to a control unit such as C3, through both 105 back contacts of a relay such as 341, back contacts of relays such as 336 and 337, right inner back contact of a relay such as 335, brush and normal terminal of a bank such as 327 of a switch such as IR1, normal terminal 110 and brush of a bank such as 355 of a switch 115 120

- such as IR2, through the right-hand back contact of a relay such as 332, and through a resistance such as 343, to battery. The circuit for operating relay 157 is traced from 5 ground on conductor 129, through the winding of relay 157, right outer back contact of relay 159, next-to-the-inner right-hand front contact of relay 158, upper brush and terminal of bank 123 over a test conductor similar 10 to conductor 198 to battery in a control unit similar to C3. The operation of either of these relays prevents the further advance of switch RM2. If relay 157 operates, it connects the winding of relay 161, through the 15 front contact of relay 157 and back contact of relay 156 to ground at the middle left-hand back contact of relay 162, thereby operating relay 161. If relay 156 or both of relays 156 and 157 operate, relay 161 is not 20 operated; but relay 162 is operated through the front contact of relay 156 to ground at the middle left-hand back contact of relay 162; the right inner front contact of relay 162 is closed to lock this relay, to the ground at 25 the left inner front contact of relay 130, before its operating circuit is opened at its middle left-hand back contact. If relay 161 operates, it also causes the operation of relay 162 by connecting the winding of relay 162 30 through the left outer front contact of relay 161 to the front contact of relay 157. With only relay 162 operated, the winding of relay 156 is short-circuited through the inner right-hand back contact of relay 161, the 35 next-to-the-inner right-hand front contact of relay 162, and the outer right-hand front contact of relay 136 to ground on conductor 129. With both of relays 161 and 162 operated, the winding of relay 157 is short-circuited 40 through the inner right-hand front contact of relay 161, the next-to-the-inner right-hand front contact of relay 162, and the outer right-hand front contact of relay 136 to ground on conductor 129. Relays 156 and 157 are thus 45 released as soon as they have caused the operation of relay 161, or relays 161 and 162 as the case may be. Relay 161 controls the connections to the brushes of switch RM2 so that the lower ones of brushes 121, 122 and 124 50 are operatively effective, to the exclusion of the upper brushes, if the idle set of terminals is found by the lower one of brushes 123; and so that the upper one of brushes 121, 122 and 124 are operatively effective, to the exclusion 55 of the lower brushes, if the idle set of terminals is found by the upper one of brushes 123. Relay 162 opens the circuit for holding relay 158 so that relay 158 releases. 60 Should the first sets of terminals in the selected group of switch RM2 be busy, so that neither of relays 156 and 157 are operated, stepping magnet 120 is operated to advance the brushes of switch RM2 until an idle set of terminals or the last set of terminals in 65 the selected group is reached. The circuit for operating magnet 120 is the same as herein-before described. Relay 156, or relay 157, or both of these relays, operate to prevent the further advance of switch RM2 as soon as in idle set of terminals is reached. Should 70 all of the terminals in this group be busy, relay 135 operates when brush 125 reaches the last terminal in the group to prevent the further advance of the switch and relay 135 then closes a circuit for operating relay 159; 75 this circuit may be traced from battery through its winding, left outer front contact of relay 158, next-to-the-outer right-hand front contact of relay 136, front contact of relay 135, back contacts of relays 157 and 156, 80 to ground at the middle left-hand back contact of relay 162. Relay 159 opens the testing circuits for relays 156 and 157, opens the starting conductor 180 to the register-translators, and connects ground through resistance 160 and the outer left-hand front contact of relay 159 and the left outer back contact of relay 165 to hold relay 170 operated, if already operated as hereinafter described. 85 Relay 159 also releases relay 150, thereby connecting ground through the secondary winding of busy tone transformer 169, the right inner front contact of relay 158, the outer right-hand back contact of relay 150, condenser 189, right-hand front contact of relay 159, to the conductor connected to the right-hand winding of line relay 131. A busy tone is thus transmitted to the calling subscriber. 90
- It will be assumed that an idle set of terminals was found by the lower one of brushes 123 so that relay 161 is not operated. With relay 162 operated the winding of relay 164 is connected across conductors 196 and 197 which lead to the selected intermediate selecting switch CS3; this connection may be traced from conductor 196, through the selected terminal and lower brush of bank 121, right outer back contact of relay 161, middle right-hand front contact of relay 162, 100 winding of relay 164, right inner back contact of relay 165, middle right-hand back contact of relay 161, through the lower brush and selected terminal of bank 122, to conductor 197. Since conductors 196 and 197 are connected through the outer left-hand back contacts of relay 339 of control unit C3 and through the windings of line relay 331 to battery and ground, relays 164 and 331 operate. 105 Relay 164 closes a circuit from battery through the winding of relay 165, front contact of relay 164, inner left-hand back contact of relay 133, to ground at the middle left-hand front contact of relay 162. Relay 165 locks through its left inner front contact 110 and the right inner front contact of relay 162, to ground at the left inner front contact of relay 130. Relay 165 sends a signal to the register-translator which has connected itself with the control unit C2 as hereinafter 115 120 125 130

described, and also transfers the connections from the windings of line relay 331 over conductors 196 and 197 from the winding of relay 164 to the terminals of control unit C2 in the banks of the finder switches of the associated register-translators. Relay 164 releases but line relay 331 of control unit C3 is held operated by a bridge in the register-translator RT as hereinafter described. Relay 331 of control unit C3 closes a circuit for operating relay 332; and relay 332 opens the connection from test conductor 313 to and through resistance 343 to battery, and connects conductor 313, through the left back contact of relay 341, over conductor 349, directly to ground at the left outer front contact of relay 332. Line relay 181 remains connected to the calling line to receive the impulses created by the dialing of the remaining digits of the called number and to transmit these impulses to the register-translator.

The aforementioned operation of relay 162 is also effective to cause the operation of stepping magnet 100 of conversational switch CS2 in a circuit from battery through the winding of magnet 100, terminal and brush of bank 113 of switch RM1, left inner front contact of relay 162, back contacts of relays 135, 157 and 156, right outer front contact of relay 139, brush and terminal of bank 112 of switch RM1, to ground at the interrupter contacts of magnet 100. Magnet 100 is thus alternately operated and released to advance the brushes 101 to 104 inclusive until they reach the terminals of the trunk selected by the by-path switch RM2; at which time relay 135 operates in a circuit which is traced from battery through its winding, next-to-the-outer right-hand front contact of relay 162, left inner back contact of relay 161, lower brush and terminal of the selected set in bank 124 of switch RM2, corresponding terminal and brush of bank 104 of switch CS2, terminal and brush of bank 119 of switch RM1, right outer front contact of relay 162, to ground at the right outer back contact of relay 158 (this relay having released when relay 162 operated).

The aforementioned connection of ground over conductor 180 to the register-translators associated with control unit C2 at the time of the operation of relay 150, was effective to operate the starting relay 211 of translator RT and the corresponding relay of the other idle register-translators. We will assume that the translator RT is the one used on the connection being described, and will limit the description to the operation of this translator. The connection from conductor 180 to operate relay 211 may be traced through the normal terminal and brush of bank 247 of numerical switch NS, the brush and normal terminal of bank 244, to the winding of relay 211. Relay 211 closes a circuit for operating the stepping magnet 200

of finder switch RF to advance the brushes of this switch until the terminals, to which control unit C2 is connected, are reached. The circuit for operating magnet 200 is traced from battery through its winding and interrupter contacts, right inner front contact of relay 211, normal terminal and brush of bank 283 of sender switch SM, normal terminal and brush of bank 242 of numerical switch NS, to ground at the back contact of relay 212. When the brushes of switch RF reach the terminals connected to control unit C2, a circuit is closed from ground at the right outer front contact of relay 211, through the winding of relay 212, brush and terminal of bank 209, through the left outer back contact of relay 159 of control unit C2, middle left-hand front contact of relay 150, to the windings of relay 170. Relays 212 and 170 operate, the operation of relay 212 opening the circuit for operating magnet 200 to prevent the further advance of switch RF. Relays 212 and 170 lock in a circuit from battery through the right-hand winding and left inner front contact of relay 170, the left outer back contact of relay 165 (this relay not having been operated at this time), the left outer back contact of relay 159, terminal and brush of bank 209 of switch RF, winding of relay 212 to ground at the left outer front contact of relay 212.

When the register-translator makes connection with the control unit C2 it does not know initially what type of call is being made but a discriminating signal is received, from control unit C2, when relay 165 operates as hereinbefore described, over one of conductors 181, 182 or 183 to operate one or more of relays 215, 216 and 217 and thereby indicate whether the call is one requiring translation, requiring the sending of numerical digits only, or requiring the sending of both office code and numerical digits. The call which is involved in the description of this invention being a call completed through a tandem office, ground is received over conductor 183; this connection may be traced from conductor 183, through the outer right-hand front contact of relay 168, left-hand back contact of relay 163, right-hand front contact of relay 170, outer left-hand front contact of relay 165, to ground at the back contact of relay 151. The ground thus connected to conductor 183 is extended through the terminal and brush of bank 208, through the left-hand winding of relay 217 and through the left inner front contact of relay 212 to battery. Relay 217 operates thereby closing the aforementioned circuit for holding line relay 331 of control unit C3, after relay 165 of control unit C2 operates; this circuit is traced from brush 201 of switch RF through the middle right-hand front contact of relay 217, back contact of relay 234, inner right-hand front contacts of relays 212 and 217, to brush 202, the right-

hand winding of relay 217 being short-circuited by the contact of relay 212. Relay 217 also closes a circuit for operating stepping magnet 220 of code switch CM; 5 this circuit is traced from battery through the winding and interrupter contacts of magnet 220, back contact of relay 226, back contact of the continuity springs of relay 233, to ground at the outer left-hand front contact 10 of relay 217. All of the positions which lead to the same group of control units, one of which C2 was selected in response to the first digit of the office code, are strapped together and connected to one position in the bank 221 15 of code switch CM so that the code switch has a home or starting position for each group of control units to which the register-translator has access. Other positions between these home positions correspond to office 20 codes all having the same first digit as the home position with which they are associated. When switch CM has advanced to the home or starting position corresponding to the first digit dialed (that is to the position 25 corresponding to the control unit group which includes the unit C2) a circuit is closed from battery through the winding of relay 226, right-hand back contact of relay 216, brush and terminal of bank 207, terminal and 30 brush of bank 221, inner left-hand front contact of relay 217, to ground at the inner left-hand back contact of relay 215. Relay 226 operates thereby opening the circuit for operating magnet 220, so that switch CM stops 35 in the home or starting position corresponding to the first digit dialed. Relay 226 closes a circuit for operating relay 233; this circuit is traced from battery through the winding of relay 233, back contact of relay 229, conductor 218, right-hand front contact of relay 226, back contact of the continuity springs of relay 233, to ground at the outer left-hand front contact of relay 217. Relay 233 locks 40 over conductor 218 through the front contact of its continuity springs to the same ground. Relay 226 also closes a circuit from the ground at the outer left-hand front contact of relay 217, through the back contact of the continuity springs of relay 233 and the right- 45 hand front contact of relay 226, over conductor 218, brush and normal terminal of bank 281 of sender switch SM, right-hand back contact of relay 227, conductor 236, outer left-hand back contact of relay 215, inner left-hand back contact of relay 235, winding of relay 228, and through resistance 219 50 to battery. Relay 233 maintains this circuit through the front contact of its continuity springs instead of through the back contact of these springs and the right-hand front contact of relay 226. Relay 228 is not operated unless or until the contacts of interrupter 231 are opened, there otherwise being 55 a short circuit around the winding of relay 228 from resistance 219 and through the back 60 contact of relay 228, through the left-hand back contact of relay 227, and through the upper contacts of interrupter 231 to conductor 218. When interrupter 231 actuates its contacts, relay 228 operates and locks by 70 connecting conductor 236 through its inner left-hand front contact and the back contact of relay 230 to conductor 218. Relay 228 closes a circuit for operating relay 227; this circuit may be traced from battery through the winding of relay 227, right-hand front contact of relay 228, left-hand front contact of relay 226, left-hand back contact of relay 216, to ground on conductor 218. When relay 227 operates it closes an impulsive 75 circuit from the ground on conductor 218, through the upper contacts of interrupter 231, the front contact of relay 227, winding of relay 230, brush and terminal of bank 208 of switch RF, middle left-hand back contact 80 of relay 149 in control unit C2, brush 144 of switch RM3 and strapped terminals of the routing group (to which switch RM3 was advanced by the third digit dialed), and through the outer left-hand front contact of 85 relay 168, to the winding of stepping magnet 140 of switch RM3. Every time the contacts of interrupter 231 close and open, relay 230 and magnet 140 operate and release. The first operation of relay 230 causes the release 90 of relay 228, and each operation of relay 230 closes a holding circuit through its left-hand front contact for relay 227. Each operation of relay 230 also connects the ground on conductor 218 through its right-hand front contact to the winding of stepping magnet 220 of code switch CM. Thus the brushes of switch RM3 in control unit C2 and the brushes of code switch CM are advanced one 95 step for every closure of the contacts of interrupter 231 after relay 227 operates, until the brushes of switch RM3 have been advanced beyond the last strapped routing group terminal in bank 144. Relay 227 is a 100 slow-to-release relay and remains operated during the advance of code switch CM. As soon as the brushes of switch CM have advanced from the home or starting position, to which it was initially advanced, relay 226 105 releases. Relay 227 releases when the impulsive circuit is opened at brush 144. In this manner the brushes of code switch CM have been advanced to a position which represents the office code of the called number. 110

The register-translator is now ready to transmit impulses for controlling the selecting operation of the intermediate selecting stage and also to transmit the office code impulse or impulses to the tandem office. The 115 release of relay 227, after the setting of code switch CM, again closes the circuit for operating relay 228 as hereinbefore described and relay 228 reoperates if, or soon as, the contacts of interrupter 231 are open. When re- 120

125

130

lay 228 reoperates, it connects the ground on conductor 218, through the upper contacts of interrupter 231, the left-hand back contact of relay 227, outer left-hand front contact of relay 228, to the winding of stepping magnet 280 of sender switch SM. Magnet 280 operates when the interrupter closes its contacts and releases when the interrupter opens its contacts thereby advancing the brushes of switch SM to position 2. Relay 234 now operates in a circuit from battery through its winding, next-to-the-outer left-hand back contact of relay 215, terminal 2 and brush of bank 281 to ground on conductor 218. Relay 234 opens the short-circuit around the lower contacts of interrupter 231 thus rendering these contacts effective to interrupt the connection from brush 201 of switch RF through the middle right-hand front contact of relay 217, lower interrupter contacts, inner right-hand front contacts of relays 212 and 217 to brush 202 of switch RF. Since the terminals with which brushes 201 and 202 are in contact connect through the inner right-hand front contacts of relay 165 and the back contacts of relay 161, through the lower brushes 121 and 122 over conductors 196 and 197, through the outer left-hand back contacts of relay 339, to the windings of line relay 331 of control unit C3, line relay 331 is released each time the lower contacts of interrupter 231 are opened after relay 234 operates, causing the operation of control unit C3 as hereinafter described. At the same time the upper contacts of interrupter 231 continue to operate and release magnet 280 of switch SM so that the brushes of this switch are advanced until the proper number of impulses have been transmitted to control the selective operation of the intermediate selecting stage.

The terminals of bank 282 of sender switch SM are divided into groups corresponding to the digits of the translated office code. Terminals 3 to 12 constitute the first group and represent the first digit of the translated code. They are connected as required to the terminals in bank 222 of code switch CM. Terminals 15 to 24 constitute the second group and represent the second digit of the translated code; they are connected as required to the terminals of bank 223 of switch CM. Terminals 27 to 36 constitute the third group and represent the third digit of the translated code; they are connected as required to the terminals of bank 224 of switch CM; and if a fourth office code digit is used, terminals 39 to 48 are connected as required to the terminals in bank 225 of switch CM. When brush 282 reaches the terminal corresponding to the first digit of the translated code, relay 235 operates in a circuit from battery through its winding and continuity contacts, brush and terminal of bank 282 of sender switch SM, terminal and brush of bank 222 of code

switch CM, through the inner right-hand front contact of relay 233, to ground at the inner left-hand back contact of relay 215. Relay 235 short-circuits the lower interrupter contacts of interrupter 231 to prevent further opening of the circuit of line relay 331, and opens the circuit for holding relay 228. Relay 235 closes a circuit from battery through the winding and interrupter contacts of magnet 280, inner right-hand front contact of relay 235, next-to-the-outer left-hand back contact of relay 215, strapped terminals 2 to 12 and brush of bank 281, to ground on conductor 218. The brushes of switch SM are thus advanced to position 13 in which the circuit for relay 234 and magnet 280 is opened. Relay 234 is a slow-to-release relay so that it does not release during the movement of switch SM but releases when position 13 is reached. Relay 235 also releases slowly after its holding circuit is opened by the release of relay 234.

When relay 235 releases, relay 228 reoperates and switch SM is advanced to position 14 in the same manner that it was advanced to position 2. Relays 234 and 235 and interrupter 231 now operate to advance switch SM from position 14 to position 25 in the same manner that it was advanced from position 2 to position 13; and during this advance, the impulses corresponding to the second translated digit, as indicated by the terminal with which brush 223 of code switch CM is in contact, are transmitted in the same manner that the impulses corresponding to the first translated digit were transmitted. In like manner the remaining digits of the translated office code are transmitted during the advance of sender switch SM from position 26 to 36 and from position 38 to 48. If the translated office code consists of a fewer number of digits, the corresponding positions of switch SM are passed by since the contacts of the remaining banks of code switch CM will be connected to as many of terminals 37, 25 and 13 in bank 281 as is necessary to hold relays 234 and 235 operated until switch SM reaches position 49.

During the time that the code switch CM is being positioned and the translated office code digits are being transmitted, the numerical impulses have been received by line relay 131 of control unit C2 and re-transmitted to the numerical switch NS of the register-translator RT. The circuit for operating the stepping magnet 240 of switch NS may be traced from battery through its winding, back contact of the continuity springs of relay 214, winding of relay 213, outer right-hand front contact of relay 212, brush and terminal of bank 206 of switch RF, inner left-hand front contacts of relays 166 and 136, right-hand front contact of relay 130, winding of relay 133, to ground at the back contact of relay 131. Each operation and release

of magnet 240 advances switch NS one position. Relay 213 operates in series with magnet 240 and being slow to release it remains operated until all of the impulses have been received. Relay 213 closes an obvious circuit for operating relay 214 which is also of the slow-to-release type. When relay 213 releases at the end of the first series of impulses, and before relay 214 releases, a circuit is closed for operating that combination of register relays 251, 252, 253 and 254 as corresponds to the first numerical digit (the thousands digit) as indicated by the position to which the switch NS was advanced, and as controlled by the wiring on terminals 2 to 11 of banks 244, 245, 246 and 247. For instance, assuming the first numerical digit to be 2, a circuit is closed from battery through the windings of relays 251, 252 and 253 and brushes 244, 245 and 246 in position 3, through the inner left-hand front contact of relay 214 and the back contact of relay 213 to ground at the outer left-hand front contact of relay 212. Relays 251, 252 and 253 operate and lock through their outer upper front contacts, over conductor 237, to the same ground. When relay 214 releases the circuit for operating the register relays is opened but numerical switch NS is advanced until it reaches position 12; the circuit for operating magnet 240 is traced from battery through its winding and interrupter contacts, outer right-hand back contact of relay 214, strapped terminals 2 to 11 inclusive and brush of bank 241, to ground on conductor 237. The numerical switch NS remains in position 12 until the impulses corresponding to the next numerical digit (the hundreds digit) are received from relay 131.

Switch NS is now advanced, under control of impulses received by relay 131 when the second numerical digit is dialed, to the corresponding one of the positions 13 to 22 in the same manner that it was advanced to the position corresponding to the first numerical digit. That combination of register relays 261 to 264 inclusive, which corresponds to this position, is then operated and locked in the same manner that the register relays 251 to 254 inclusive were operated. The switch NS continues to be advanced, until position 23 is reached, in the same manner that it was advanced to position 12. In like manner the third numerical digit (the tens digit) is received by switch NS and transferred to register relays 271 to 274 inclusive. The fourth or units digit of the called number is likewise received by switch NS, relay 214 being held operated through the right outer front contact of relay 233 and the terminals and brush of bank 241 to prevent the further advance of the numerical switch until all of the numerical digits have in turn been transmitted to the tandem office.

Since either relay 251 or relay 253 is always operated, according to the thousands digit, relay 228 reoperates as soon as the thousands digit has been registered; the circuit for relay 228 is traced from battery through its winding, inner left-hand back contact of relay 235, outer and next-to-the-inner left-hand back contacts of relay 215, conductor 238, lower front contact of relay 251 (or 253), terminal 49 and brush of bank 281 of switch SM, to ground on conductor 218. Relay 228 locks under control of relay 230 as hereinbefore described. The sender switch SM and relays 234 and 235 now operate (under control of interrupter 231 and register relays 251 to 254 inclusive) to transmit a train of impulses corresponding to the first numerical digit, terminals 51 to 60 inclusive of bank 282 being connected to the contacts of the thousands register relays to secure this result. Thus the thousands digit being 2, as already assumed, two impulses are transmitted as the sender switch steps from position 50 to position 52; and in position 52 relay 235 operates, the circuit for operating relay 235 being traced from battery through its winding and continuity contacts, brush and terminal 52 of bank 282, middle lower back contact of relay 254, inner upper front contacts of relays 252 and 251, to ground at the inner upper front contact of relay 253. The switch SM continues to be advanced until position 61 is reached at which time relay 234 releases. The switch SM remains in position 61 until the hundreds digit has been registered as indicated by the operation of one of relays 261 or 263. Relay 228 then reoperates and the SM switch is advanced (under the control of relays 234 and 235, interrupter 231, and register relays 261 to 264 inclusive), to transmit a train of impulses corresponding to the second or hundreds numerical digit, terminals 63 to 72 inclusive of bank 282 being connected to the contacts of the hundreds register relays to secure this result. The switch SM continues to be advanced until position 73 is reached at which time relay 234 releases. The switch SM remains in position 73 until all of the impulses corresponding to the tens digit have been received as indicated by the operation of either one of register relays 271 or 273. Impulses corresponding to the tens digit are then transmitted during the advance of switch SM from position 73 to 85 (under control of relays 234 and 235, interrupter 231, and register relays 271 to 274 inclusive), terminals 75 to 84 of bank 282 being connected to the contacts of the tens register relays to secure this result. Relay 234 releases to stop switch SM when position 85 is reached. The switch SM remains in position 85 until all of the impulses corresponding to the units digit have been received, as indicated by the operation of register relay 271 or 273 and the operated condition of relay 214 which

is held through terminals 35 to 45 of bank 241 of switch NS. Impulses corresponding to the units digit are then transmitted during the advance of switch SM from position 5 to 97 (under control of relays 234 and 235, interrupter 231, and the banks 244 to 247 inclusive of the switch NS), terminals 87 to 96 inclusive of bank 282 being connected to terminals 35 to 44 inclusive of banks 244 to 247 inclusive of switch NS to secure this result.

All of the numerical impulses have now been transmitted by the register-translator and with the brushes of switch SM in position 97 a circuit is closed from the ground on conductor 218, brush and terminal 96 of bank 281, brush and terminal of bank 210 of switch RF, to the winding of relay 159 of control unit C2. Relay 159 opens the circuit through brush 209 of switch RF so that relay 212 of register-translator RT and relay 170 of control unit C2 release. The release of relay 212 opens the circuit through the left-hand winding of relay 217; but it also removes the short-circuit around the right-hand winding of relay 217, so that this relay remains operated and the circuit through brushes 201 and 202 to the windings of relay 331 of control unit C3 is maintained until control unit C2 returns to normal. When the circuit through these brushes is opened by the control unit C2, relay 217 releases and then relays 233 and 214 release. The release of relay 214 closes a circuit from battery through the winding and interrupter contacts of magnet 240, right outer back contact of relay 214, off-normal terminals and brush of bank 242 of switch NS, to ground at the back contact of relay 212. The brushes of switch NS are thereby advanced to their normal position. When switch NS reaches its normal position the stepping-magnet 280 of switch SM is energized in a circuit from battery through its winding and interrupter contacts, off-normal terminals and brush of bank 283, normal terminal and brush of bank 242 of switch NS, to ground at the back contact of relay 212. The brushes of switch SM are thereby advanced to their normal position. The code switch CM and finder switch RF remain in the positions in which they are standing until advanced therefrom on the next call.

The aforementioned operation of relay 159 also closes a circuit from battery through the winding of relay 105 of conversational switch CS2, terminal and brush bank 114 of switch RM1, inner right-hand front contact of relay 139, resistance 184, next-to-the-outer right-hand front contact of relay 165, next-to-the-inner left-hand front contact of relay 159, inner right-hand front contact of relay 162, to ground at the left inner front contact of relay 130. Relay 105 operates in this circuit thereby extending the talking con-

ductors of trunk 99 through the inner left-hand front contacts of relay 105, and through brushes 101 and 102, over trunk 199, to the conversational switch CS3. Relay 105 disconnects the sleeve conductor of trunk 99 from control unit C2 and connects this conductor through its outer left-hand front contact, and through brush 103, to ground in the succeeding selecting stage as hereinafter described, relay 105 being locked to the same ground. Relay 105 also disconnects test conductor 98 from the control unit C2.

The aforementioned operation of relay 159 also opens the circuit for holding relay 150 since this circuit included the inner left-hand back contact of relay 159. The release of relay 150 causes the release of relay 130 since the circuit for holding relay 130 included the inner right-hand front contact of relay 150. The release of relay 130 opens the circuits for relays 136, 137, 162 and 165. The release of relay 137 opens the circuit for relay 139. The release of relay 139 causes the release of relay 131; and the release of relay 131 causes the release of relay 132. The release of relay 132 disconnects ground from conductor 129 thereby causing the release of relay 166. The release of relay 166 releases relays 168 and 134. The release of relay 162 closes a circuit from ground at its middle left-hand back contact, back contacts of relays 156, 157 and 135, inner left-hand back contact of relay 162, off-normal terminals and brush of bank 126 of switch RM2, through the interrupter contacts and winding of magnet 120 to battery. Magnet 120 thereby advances the brushes of switch RM2 to normal. The release of relay 136 closed a circuit from battery through the winding of magnet 110, right inner back contact of relay 136, inner right-hand back contact of relay 130, brush and off-normal terminals of bank 115 of switch RM1, back contact of relay 137, through the interrupter contacts of magnet 110 to ground. Magnet 110 thereby advances the brushes of switch RM1 to their normal position. The release of relay 136 also closes a circuit from ground at its left outer back contact, back contact of relay 134, off-normal terminals and brush of bank 145 of switch RM3, and through the interrupter contacts and winding of magnet 140 to battery. Magnet 140 thereby advances the brushes of switch RM3 to their normal position. Control unit C2 is now ready for the next call, conductor 106 being connected through resistance 127 to battery as hereinbefore traced.

The operation of control unit C3 and conversational switch CS3 will now be described. The aforementioned operation of relay 332 (when relay 331 operated in the circuit through the translator RT, as hereinbefore described), was also effective to close a circuit for operating relay 334; this circuit is

traced from battery through the winding of relay 334, right outer back contact of 339, right inner front contact of relay 332, brush and normal terminal of bank 355 of switch 5 IR2, normal terminal and brush of bank 327 of switch IR1, right inner back contact of relay 335, back contacts of relays 337 and 336, back contact of the continuity springs of relay 341, to ground at the left outer front contact of relay 332. Upon receiving the impulses corresponding to the first translated office code digit from the register-translator RT, relay 331 is alternately released and reoperated. The first release of relay 331 10 closes a circuit from ground at its back contact, through the winding of relay 33, middle left-hand front contact of relay 332, outer left-hand back contact of relay 335, through the winding of stepping-magnet 20 320 of switch IR1 to battery. Relay 333 and magnet 320 operate. When relay 331 reoperates, magnet 320 releases thereby advancing the brushes of switch IR1 to position 2. Each release and reoperation of relay 331 25 causes the operation and release of magnet 320 thereby advancing the brushes of switch IR1 to a position which corresponds to the number of impulses received by relay 331. Relays 332 and 333 are both slow in releasing, so that relay 332 does not release on account of the release of relay 331 during the receipt of impulses, and relay 333 does not release until all of the impulses in the train 30 have been received.

35 When the brushes of switch IR1 are advanced from normal to position 2, relay 334 releases thereby closing a circuit from battery through the winding and interrupter contacts of magnet 350 of switch IR2, left 40 inner back contact of relay 339, left-hand back contact of relay 334, brush and normal terminal of bank 356 of switch IR2, front contact of relay 333, conductor 349, to ground at the left outer front contact of relay 332. Magnet 350 advances the brushes of switch IR2 to position 2. Brush 356 is now connected through the off-normal terminals of its bank to ground at the next-to-the-outer left-hand back contact of relay 335 so that magnet 350 continues to operate and release until relay 334 reoperates. The 45 terminals in bank 327 of switch IR1 are connected to terminals in the bank 355 of switch IR2, each of these terminals in the bank 355 being the first of a group which correspond to the impulses received by relay 331. When brush 355 engages the first terminal of the group corresponding to the position in which the brushes of switch IR1 are standing, relay 334 reoperates in a circuit from battery through its winding, right outer back contact of relay 339, right inner front contact of relay 332, brush and marked terminal of bank 355 of switch IR2, terminal and brush 50 of bank 327 of switch IR1, right inner back

contact of relay 335, back contacts of relays 337 and 336, back contact of the continuity springs of relay 341, over conductor 349 to ground at the left outer front contact of relay 332. Relay 334 opens the circuit for operating magnet 350, so that the brushes of switch IR2 are stopped on the first set of terminals in the marked group. Relay 334 closes a circuit for operating relay 335; this circuit is traced from battery through the right-hand winding of relay 335, left outer back contact of relay 342, right-hand back contact of relay 333, left-hand front contact of relay 334, brush and off-normal terminals of bank 356 of switch IR2, to ground at the next-to-the-outer left-hand back contact of relay 335. Relay 335 closes its inner left-hand front contact before it opens its next-to-the-outer left-hand back contact, so that relay 335 is locked through its left-hand winding and inner front contact to ground on conductor 349. Relay 335 opens the circuit for relay 334, so that relay 334 releases. Before relay 335 operated, the positioning of brushes 323 and 324 of switch IR1 was effective to operate that combination of relays 358 and 359 as corresponds to the charging zone indicated by the impulses representing the first translated office code digit. Although on a tandem call the same group of trunks is selected in response to several digits, as indicated by the strapping of terminals 10, 11 and 12 in bank 327, these different digits are effective to operate a different combination of relays 358 and 359, depending upon the zone within which the called local office is located. The operation of relay 358 is controlled by brush 321 and the operation of relay 359 is controlled by brush 322. Thus only relay 358 is operated if the brushes of switch IR1 are advanced to positions 4, 8 or 11; only relay 359 is operated if the brushes are advanced to position 2, 3, 5 or 10; both of relays 358 and 359 are operated if the brushes are advanced to position 7 or 12; and neither of these relays is operated if the brushes are advanced to position 6 or 9. When relay 335 operates relays 358 and 359 are locked, if operated, to ground at the two next-to-the-outer right-hand front contacts of relay 335.

If one or both of the first sets of terminals, in the selected group in the banks of switch IR2, are idle one or both of test relays 336 and 337 operate to prevent the further advance of switch IR2. But if the first sets of terminals in the selected group are busy the aforementioned release of relay 334 again closes the circuit for operating magnet 350 so that the brushes of switch IR2 are advanced until an idle set of terminals are found in the selected group or until the last set of terminals in the group is reached. The circuit for operating test relay 336 is traced from ground on conductor 349, through the wind-

ing of relay 336, outer right-hand back contact of relay 342, middle right-hand back contact of relay 339, third right-hand front contact of relay 335, lower brush 353 and idle 5 test terminal, over test conductor 398 to the outgoing trunk circuit TR, through the inner upper back contact of relay 404 and winding of relay 402 to battery; relay 402 does not operate in this circuit. The circuit for operating relay 337 is traced from ground on conductor 349, right inner back contact of relay 342, winding of relay 337, inner right-hand back contact of relay 339, next-to-the-inner right-hand front contact of relay 335, 10 through upper brush 353 and test terminal, to battery in the selected idle outgoing trunk repeater in the same manner as traced for test relay 336. If relay 336 operates it closes a circuit for operating relay 339, from battery through the winding of relay 339, front contact of relay 336, back contact of the continuity springs of relay 341, to ground on conductor 349. Relay 339 locks through its 15 inner left-hand front contact to the same ground and, when fully energized, disconnects the test relays 336 and 337 from brushes 353. If relay 337 operates it closes an obvious circuit for operating relay 338; and relay 338 then closes an obvious circuit 20 for operating relay 339. The operation of either of relays 336 or 337 opens the circuit for operating magnet 350. Relay 338 controls the connections to brushes 351 and 352 so that either the upper or the lower of these 25 brushes is operatively effective, in extending the connection, to the exclusion of the other set depending upon which of the upper or lower of test brushes 353 have found an idle set of terminals. We will assume the selected set of terminals to be in the lower banks 351, 352 and 353 so that relay 338 is not operated. With relay 339 operated, the ground on conductor 349 is connected through the left-hand back contact of relay 338, the next-to-the-outer right-hand front contact of relay 339, the third right-hand front contact of relay 335, and through test brush 353, to conductor 398 to cause the operation of relay 402 in the trunk circuit TR. 30

If all of the terminals in the selected group are busy relay 334 operates when the last set of terminals is reached, in a circuit from battery through its winding, right outer back contact of relay 339, right inner front contact of relay 332, brush and last terminal of the selected group in bank 355, conductor 360, right inner front contact of relay 335, back contacts of relays 337, 336 and 341, to ground on conductor 349. Relay 334 opens 35 the circuit for magnet 350 and closes a circuit for operating relay 342, from battery through the winding of relay 342, middle left-hand front contact of relay 335, left-hand front contact of relay 334, brush and off-normal terminals of bank 356, next-to- 40

the-outer left-hand front contact of relay 335, back contacts of relays 337, 336 and 341 to ground on conductor 349. Relay 342 is a slow-to-operate relay and does not operate during the time that both of relays 335 and 334 are operated upon the initial operation of relay 335; but when the last set of terminals in the group are reached, relay 334 holds the circuit for relay 342 closed until this relay operates. Relay 342 causes a busy tone 70 to be transmitted to the calling subscriber by connecting the secondary winding of transformer 348, through condenser 347, the right outer front contact of relay 342, and through the next-to-the-inner left-hand front contact of relay 335, to the right-hand winding of line relay 331. 75

When relay 339 operates in consequence of the selection of an idle set of terminals as hereinbefore described, it closes a circuit for operating magnet 320 of switch IR1, from battery through the winding of magnet 320, outer left-hand front contact of relay 335, interrupter contacts of magnet 320, to ground at the back contact of test relay 340. The 80 brushes of switch IR1 are thereby advanced until the terminals connected to switch CS3 are reached, at which time the circuit for magnet 320 is opened by the operation of test relay 340. The circuit for operating relay 340 is traced from battery through its winding, brush and terminal of bank 323, back contact of the continuity springs of relay 305, over the sleeve conductor of trunk 199, through brush 103 and the right inner front 85 contact of relay 105, to the ground which is holding relay 105 operated as hereinbefore described. Relay 340 closes the circuit for operating relay 341; and relay 341 connects the ground on conductor 349 through its left-hand front contact to the winding of relay 340 to hold relay 340 operated; this ground is also effective temporarily to hold relays 105, 55, and 3 operated. Relay 341 also disconnects the ground on conductor 349 from 90 test conductor 313. 95

With both of relays 339 and 341 operated, a circuit is closed from battery through the winding and interrupter contacts of stepping magnet 300 of switch CS3, terminal and brush of bank 326, right-hand back contact of relay 334, middle right-hand front contact of relay 341, to ground at the right inner front contact of relay 339. The brushes of switch CS3 are thereby advanced until brush 304 makes contact with the terminal which is connected to the marking terminal of the selected outgoing trunk TR in the bank 354 of switch IR2; at which time relay 334 re-operates to open the circuit for magnet 300 and thus stops the brushes 301 to 304 inclusive on the terminals of trunk 399 leading to the outgoing trunk circuit TR. The circuit for operating relay 334 is traced from battery through its winding, right outer front 100

contact of relay 339, right inner back contact of relay 338, lower brush and marked terminal of bank 354, corresponding terminal and brush of bank 304 of switch CS3, 5 terminal and brush of bank 327 of switch IR1, right outer front contact of relay 341, back contacts of relays 337 and 336 to ground at the right inner front contact of relay 341. Relay 334 also closes a circuit for operating 10 relay 342; this circuit is traced from battery through the winding of relay 342, middle left-hand front contact of relay 335, left-hand front contact of relay 334, brush and off-normal terminals of bank 356, next-to-15 the-outer left-hand front contact of relay 335, back contacts of relays 337 and 336, to ground at the right inner front contact of relay 341. Relay 342 closes a circuit for operating relay 305, from battery through 20 the winding of relay 305, terminal and brush of bank 324 of switch IR1, left outer front contact of relay 342, right-hand front contact of relay 334, middle right-hand front contact of relay 341, to ground at the right 25 inner front contact of relay 339. Relay 305 disconnects test conductor 198 from control unit C3, extends the talking conductors of trunk 199 through its left inner front contacts and the brushes 301 and 302, over the 30 talking conductors of trunk 399 to the outgoing trunk circuit TR. Relay 305 also extends the sleeve conductor of trunk 199, through its right inner front contact, to the holding ground at the back contact of relay 309. This ground is effective as soon as relay 35 operates as hereinbefore described to hold relays 105, 55, and 3 until the connection is released by the calling subscriber as hereininafter described. Relay 305 closes a circuit 40 from battery through the middle winding of supervisory relay 306 to ground at the middle right-hand front contact of relay 305. Relay 306 is not operated at this time, it being necessary that both the middle and right-hand windings be cumulatively energized in order to operate this relay.

With switch IR1 advanced to connect with switch CS3, zone relays 307 and 308 are connected through brushes 321 and 322 so that either or both of these relays operate according to whether relays 358 and 359 in control unit C3 are operated. If either or both of relays 307 and 308 operate they lock through their right inner front contacts to ground at the middle right-hand front contact of relay 305.

The aforementioned operation of relay 339 was also effective to open the connections from impulse conductors 196 and 197 to the winding of relay 331, and to extend the impulsive circuit from the register-translator RT, through the left outer front contacts of relay 339, and the right outer back contacts of relay 338, through the lower brushes and terminals of banks 351 and 352 over con-

ductors 396 and 397, through the middle upper back contacts of relay 404, over the conductors of trunk 499, to impulse receiving apparatus in the tandem office which is represented schematically by the enclosure T. 70 Thus the remaining digits of the translated office code and the numerical digits are transmitted through the outgoing trunk circuit TR and over trunk 499 to the tandem office T. 75 The connection is then extended by the apparatus in the tandem office T over trunk 500 to the local office LO and by apparatus in the local office LO to the line 501 leading to the called subscriber B. The release of the register-translator and control unit C2 after all 80 of the impulses have been transmitted to the tandem office has already been described.

The release of relay 331 when the windings of this relay are disconnected from impulse conductors 196 and 197 by the aforementioned operation of relay 339 causes the release of relay 332. Relay 332 is slow in releasing so that a holding circuit will be provided from ground in the trunk circuit TR over conductor 398 to maintain a ground on conductor 349, so as to prevent the release of relays 340, 341, 339, 335 and 334 in control unit C3 until all of the impulses have been transmitted to the tandem office. 90

When relay 402 of trunk circuit TR operates, as hereinbefore described, it closes a circuit from ground through its inner upper front contact, middle lower back contact of relay 404, winding of relay 403, outer upper back contact of relay 404, and through resistance 407 to battery, thereby operating relay 403. The ground at the inner upper front contact of relay 402 is also extended through the winding of relay 403, over the sleeve conductor of trunk 399, through brush 303 of switch CS3 to the right outer armature of relay 305; when relay 305 operates as hereinbefore described it is locked operated through its right outer front contact, to the ground at relay 402. This circuit is also effective to hold relay 403 operated after relay 404 operates. Relay 403 closes a holding circuit for relay 402 and connects the ground at its lower front contact, through the inner upper back contact of relay 404, over conductor 398, through the terminal and lower brush of bank 353, second-from-the-inner right-hand front contact of relay 335, next-to-the-outer right-hand front contact of relay 339, left-hand back contact of relay 338, to conductor 349 to 100 prevent the release of the control circuit C3. Relay 403 connects the line conductors of trunk 399 to the windings of line relay 401 so that as soon as relay 105 operates, (in consequence of the operation of relay 159 after all 110 of the impulses have been transmitted as hereinbefore described), relay 401 operates in the circuit over the calling subscriber's line. Relay 401 connects the polarized supervisory relay 405 across the conductors of trunk 499, 120

125

130

- and closes a circuit for operating relay 404. Relay 404 locks to ground at the lower front contact of relay 402, disconnects the impulse conductors 396 and 397 from trunk 499, opens the connection from battery through resistance 407 to the winding of relay 403, and disconnects ground from test conductor 398. With relay 404 operated, relay 403 is held operated under the control of relay 401.
- 10 When the ground in trunk circuit TR is disconnected from conductor 398, and therefore from conductor 349 of control unit C3, relays 335 and 340 release. The release of relay 340 causes the release of relay 341, and 15 the release of relay 341 causes the release of relays 339 and 334. The release of relay 335 causes the release of relay 342. The brushes of switch 1R1 are now advanced to normal, the circuit for operating magnet 320 being traced from battery through its winding, left outer back contact of relay 335, left-hand back contact of relay 332, next-to-the-inner 20 left-hand back contact of relay 339, off-normal terminals and brush of bank 325, interrupter contacts of magnet 320, to ground at the back contact of relay 340. The brushes of switch IR2 are also advanced to normal, the circuit for operating magnet 350 being traced from battery through its winding and 25 interrupter contacts, left inner back contact of relay 339, left-hand back contact of relay 334, brush and off-normal terminals of bank 356, to ground at the middle left-hand back contact of relay 335.
- 30 We will assume the connection to be extended at the tandem office in accordance with the impulses received from the register-translator RT, that the called station is signalled, that the called subscriber answers, and that a supervisory circuit is closed at the tandem office, in consequence of the answer of the called subscriber, over the conductors of trunk 499 to cause the operation of relay 405 of trunk circuit TR. Relay 405 closes 35 a circuit for operating relay 406; and relay 406 reverses the connections from the line conductors of trunk 399 to the windings of relay 401 so that the current is reversed over these conductors, through the right-hand 40 winding of supervisory relay 306 of switch CS3, and over the calling line. The talking circuit is now traced from line 1, through switches LF1, LF2, CS1, CS2 and CS3, trunk 399, condensers 408, trunk 499, tandem office T, trunk 500, the called local office LO, to the called line 501. The supervisory relay 306 operates in consequence of the reversal of current through its right-hand winding and this relay locks through its 45 left-hand winding and left inner front contact, to ground at the middle right-hand front contact of relay 305. Relay 306 also connects ground from the right outer front contact of either or both of zone relays 307 and 308, through the left outer front con-
- tact of relay 306, to the winding of start relay 380 of the common charging switch Z. When relay 380 operates it closes a circuit from battery through the winding and interrupter contacts of magnet 370 of switch Z, left-hand front contact of relay 380, back contact of relay 382, to ground at the back contact of relay 381. The brushes of switch Z are thereby advanced until they reach the terminals to which the conversational switch CS3 is connected, at which time either or both of relays 381 and 382 operate, depending upon which of the zone relays 307 and 308 are operated. The circuit for operating relay 381 is traced through brush 371, to ground at the left-hand front contact of relay 307; and the circuit for operating relay 382 is traced through brush 372, to ground at the left-hand front contact of relay 308. The operation of either of relays 381 or 382 opens the circuit for magnet 370 so as to stop the advance of switch Z.
- 50 As soon after the operation of either or both of relays 381 and 382 as the pick-up lead 386 is connected to ground at the interrupter 391, either or both of relays 383 and 384 operate. The interrupter is arranged to transmit one, two or three impulses over conductors 387, 388 and 389, to operate the charging relay 309 one, two or three times as controlled by relays 383 and 384. If only relay 383 is operated, one ground impulse is transmitted over conductor 387, through the left inner back contact of relay 384, the left inner front contact of relay 383, the left-hand back contact of relay 385, brush 373, to the winding of relay 309. If only relay 384 is operated, two ground impulses are transmitted over conductor 388, right inner front contact of relay 384, left inner back contact of relay 383, left-hand back contact of relay 385, brush 373, to the winding of relay 309. If both of relays 383 and 384 are operated three ground impulses are transmitted over conductor 389, left inner front contacts of relays 384 and 383, left-hand back contact of relay 385, brush 373, to the winding of relay 309. When a complete cycle of metering impulses has been connected to conductors 387, 388 and 389, ground is connected over conductor 390, to operate relay 385 and thereby open the circuit for operating relay 309. Relay 385 locks through its continuity contacts to ground at start relay 380, and connects ground through its right outer front contact and brush 374 to short-circuit and thereby release relays 307 and 308. The release of relays 307 and 308 causes the release of relays 381 and 382 and also the release of start relay 380. The release of relay 380 opens the locking circuit of relay 385. The charging switch Z is now ready for use on another call.
- 55 Each of the aforementioned operations of relay 309, in response to the metering im-

5 pulses from interrupter 391, transfers the sleeve conductor of trunk 199 from ground to booster-battery 310, thereby causing the operation of the message register 4 of the calling line 1, the total number of meter operations corresponding to the destination of the call. Conversation may now continue between stations A and B until the connection is released. When the subscriber at station 10 A replaces the receiver on the receiver hook, line relay 401 of trunk circuit TR releases. Relay 401 opens the bridge through relay 405 across the outgoing trunk so as to cause the release of the apparatus in tandem office T and local office LO. Relay 401 also disconnects the holding ground from the winding of relay 403 so that relays 403 and 305 release. The release of relay 403 causes the release of relay 402 and the release of relay 402 causes the release of relay 404. The trunk circuit TR is now ready for use on another call.

25 The aforementioned release of relay 305 disconnects the holding ground from the sleeve conductor of trunk 199 so that relays 105, 55 and 3 release, thus rendering the line-finders LF1 and LF2 and the conversational switches CS1, CS2 and CS3 ready for use on another call.

30 What is claimed is:

1. In a telephone system, subscribers' lines, means including an automatic switch for use in establishing a connection between a calling and a called line, means associated with said switch for receiving impulses, a group of trunks connected to terminals in the bank of said switch, means for advancing the brushes of said switch to said group of trunks in response to a train of impulses corresponding to any one of a plurality of different numerical digits, another group of trunks connected to terminals in the bank of said switch, and means for advancing the brushes of said switch to said other group only in response to a train of impulses corresponding to a single numerical digit.

2. In a telephone system, a selector switch, a marking switch, groups of terminals in the bank of said selector switch, impulse receiving means associated with said marking switch, means for advancing the brushes of said marking switch to a position corresponding to the number of impulses received, means including one of the brushes of said marking switch effective in a plurality of positions to mark the same group of terminals in the bank of said selector switch, and means for advancing the brushes of said selector switch to said marked group of terminals.

3. In a telephone system, a group of conversational switches, switches comprising a marking switch and a selector switch, a common control unit for said groups of terminals in the bank of said selector switch and

corresponding groups of terminals in the banks of said conversational switches, impulse receiving means associated with said marking switch, means for advancing the brushes of said marking switch to a position corresponding to the number of impulses received, means including one of the brushes of said marking switch effective in a plurality of positions to mark the same group of terminals in the bank of said selector switch, 70 means for advancing the brushes of said selector switch to said marked group of terminals, means for selecting an idle set of terminals in said marked group, means for marking the corresponding set of terminals 75 in the banks of said conversational switches, and means for advancing the brushes of one of said conversational switches to the marked set of terminals. 80

4. In a telephone system, a selector switch, 85 a marking switch, groups of terminals in the bank of said selector switch, impulse receiving means associated with said marking switch, indicating means associated with said marking switch, means for advancing the brushes of said marking switch to a position corresponding to the number of impulses received, means including one of the brushes of said marking switch effective in a plurality of positions to mark the same 90 group of terminals in the bank of said selector switch, means including another of the brushes of said marking switch for variably operating said indicating means according to the particular one of said plurality of positions to which the marking switch is advanced, and means for advancing the brushes of said selector switch to said marked group. 95

5. In a telephone system, a group of conversational switches, a common control unit 105 for said switches comprising a marking switch and a selector switch, groups of terminals in the bank of said selector switch and corresponding groups of terminals in the banks of said conversational switches, impulse receiving means associated with said marking switch, indicating means associated with said marking switch, means for advancing the brushes of said marking switch to a position corresponding to the number of impulses received, means including one of the brushes of said marking switch effective in a plurality of positions to mark the same group of terminals in the bank of said selector switch, 110 means including another of the brushes of said marking switch for variably operating said indicating means according to the particular one of said plurality of positions to which the marking switch is advanced, and means for advancing the brushes of said selector switch to said marked group. 115

6. In a telephone system, a group of conversational switches, switches comprising a marking switch and a selector switch, a common control unit for said groups of terminals in the bank of said selector switch and

and means for advancing the brushes of one of said conversational switches to the marked set of terminals.

6. In a telephone system, a group of conversational switches, a common control unit for said switches comprising a marking switch and a selector switch, groups of terminals in the bank of said selector switch and corresponding groups of terminals in the banks of said conversational switches, impulse receiving means associated with said marking switch, indicating means associated with said marking switch, indicating means associated with each of said conversational switches, means for advancing the brushes of said marking switch to a position corresponding to the number of impulses received, means including one of the brushes of said marking switch effective in a plurality of positions to mark the same group of terminals in the bank of said selector switch, means including another of the brushes of said marking switch for variably operating said indicating means associated with said marking switch according to the particular one of said plurality of positions to which the marking switch is advanced, and means for variably operating said indicating means associated with one of said conversational switches according to the variable operation of the indicating means associated with said marking switch.

7. In a telephone system, subscribers' lines, an automatic switch for extending a connection from a calling line to a called line, a message register for said calling line, groups of trunks connected to terminals in the bank of said switch, means for receiving impulses, means for advancing the brushes of said switch to the same group of trunks in response to a train of impulses correspondingly to any one of a plurality of digits, and means for operating said message register in accordance with the number of impulses in said train.

8. In a telephone system, a calling line, a called line, a message register for said calling line, means including a selector switch and a marking switch for establishing a connection between said lines, groups of terminals in the bank of said selector switch, impulse receiving means associated with said marking switch, means for advancing the brushes of said marking switch to a position corresponding to the number of impulses received, means effective in any one of a plurality of positions of said marking switch to mark the same group of terminals in the bank of said selector switch, means for advancing the brushes of said selector switch to said marked group of terminals, and means for variably operating said message register in accordance with the particular one of said plurality of positions to which the marking switch is advanced.

9. In a telephone system, a calling line, a called line, a meter for said calling line, a group of conversational switches, means including one of said switches for establishing a connection between said lines, a common control unit for said switches comprising a marking switch and a selector switch, groups of terminals in the bank of said selector switch and corresponding groups of terminals in the banks of said conversational switches, impulse receiving means associated with said marking switch, means for advancing the brushes of said marking switch to a position corresponding to the number of impulses received, means effective in any one of a plurality of positions of said marking switch to mark the same group of terminals in the bank of said selector switch, means for selecting an idle set of terminals in said marked group, and means associated with said one of said conversational switches for variably operating said meter in accordance with the particular one of said plurality of positions to which the marking switch is advanced.

10. In a telephone system, a calling line, a called line, a message register for said calling line, means including a selector switch and a marking switch for establishing a connection between said lines, groups of terminals in the bank of said selector switch, impulse receiving means associated with said marking switch, indicating means associated with said marking switch, means for advancing the brushes of said marking switch to a position corresponding to the number of impulses received, means including one of the brushes of said marking switch effective in a plurality of positions to mark the same group of terminals in the bank of said selector switch, means including another of the brushes of said marking switch for variably operating said indicating means according to the particular one of said plurality of positions to which the marking switch is advanced, and means for variably operating said message register in accordance with the variable operation of said indicating means.

11. In a telephone system, a calling line, a called line, a meter for said calling line, a group of conversational switches, means including one of said switches for establishing a connection between said lines, a common-control unit for said switches comprising a marking switch and a selector switch, impulse receiving means associated with said marking switch, indicating means associated with said marking switch, indicating means associated with each of said conversational switches, groups of terminals in the bank of said selector switch and corresponding groups of terminals in the banks of said conversational switches, means for advancing the brushes of said marking switch to a position corresponding to the number of im-

- 5 pulses received, means including one of the brushes of said marking switch effective in a plurality of positions to mark the same group of terminals in the bank of said selector switch, means including another of the 70 brushes of said marking switch for variably operating said indicating means associated with said marking switch according to the particular one of said plurality of positions to which the marking switch is advanced, means for variably operating said indicating means associated with said one of said conversational switches according to the variable operation of the indicating means associated with said marking switch, and means for variably operating said message register in accordance with the variable 75 operation of the indicating means associated with said one of said conversational switches. 80
- 10 12. In a telephone system, a calling line, a called line, a meter for said calling line, a group of conversational switches, means including one of said switches for establishing a connection between said lines, a common 85 control unit for said switches comprising a marking switch and a selector switch, groups of terminals in the bank of said selector switch and corresponding groups of terminals in the banks of said conversational 90 switches, impulse receiving means associated with said marking switch, means for advancing the brushes of said marking switch to a position corresponding to the number of impulses received, means effective in any one of a plurality of positions of said marking switch to mark the same group of terminals in the bank of said selector switch, means for selecting an idle set of terminals in said 95 marked group, and means common to said group of conversational switches for variably operating said meter in accordance with the particular one of said plurality of positions to which the marking switch is advanced. 100
- 15 13. In a telephone system, a calling line, a called line, a meter for said calling line, a group of conversational switches, means including one of said switches for establishing a connection between said lines, a common 105 control unit for said switches comprising a marking switch and a selector switch, impulse receiving means associated with said marking switch, indicating means associated with said marking switch, indicating means associated with each of said conversational switches, groups of terminals in the bank of said selector switch and corresponding groups of terminals in the banks of said conversational 110 switches, means for advancing the brushes of said marking switch to a position corresponding to the number of impulses received, means including one of the 115 brushes of said marking switch effective in a plurality of positions to mark the same group 120 of terminals in the bank of said selector switch, means including another of the brushes of said marking switch for variably operating said indicating means associated with said marking switch according to the particular one of said plurality of positions to which the marking switch is advanced, means for variably operating said indicating means associated with said one of said conversational switches according to the variable operation of the indicating means associated with said marking switch, and means common to said group of conversational switches for variably operating said message register in accordance with the variable operation of the indicating means associated with said one of said conversational switches. 125
- 20 14. In a multi-office telephone system, an automatic switch, groups of trunks connected to the terminals of the bank of said switch, one of said groups being used for completing calls to more than one of the offices of said system, means for receiving a series of impulses and for controlling the operation of said switch to select a particular group of trunks in accordance with the number of impulses in said series, said one of the groups being selected in response to a series of any one of a plurality of numbers of impulses. 130
- 25 15. In a telephone system, subscribers' lines, a calling line, a selector switch, means for extending said line to said switch, dialing means associated with said line for use in successively creating a series of impulses for and corresponding to each digit of the number of any other line with which connection is desired, groups of trunks connected to terminals in the bank of said switch, means associated with said switch for operatively responding to the series of impulses created by the dialing of a particular one of the digits other than the last digit of said called number, and means for advancing the brushes of said switch to the same one of said groups of trunks in response to the receipt of a series of impulses corresponding to any one of a plurality of different numerical digits. 135
- 30 16. In a telephone system, subscribers' lines, a calling line, a selector switch, means for extending said line to said switch, means associated with said line for successively creating a series of impulses for each digit of the number of any other line with which connection is desired, means associated with said switch for operatively responding to a particular one of said plurality of series of impulses other than the series corresponding to the last digit of said called number, groups of trunks connected to terminals in the bank of said switch, each of said groups selectable in response to the receipt of a series of impulses corresponding to a particular one of a plurality of different numerical digits, and another group of trunks connected to ter- 140

minals in the bank of said switch selectable in response to the receipt of a series of impulses corresponding to any one of a plurality of other different numerical digits.

5 In witness whereof, I hereunto subscribe my name this 21st day of October, 1930.

ESMOND P. G. WRIGHT.

10**15****20****25****30****35****40****45****50****55****60****65**
